ABSTRACT

A taximeter in which the metering apparatus and a control circuit for the metering apparatus are enclosed in a tamperproof housing, in which the control circuit is switch operated to selectively condition the metering apparatus to prevent and provide for the registration of a fare, in which tampering with circuit connections between the taxicab's battery and the control circuit and/or with circuit connections between one or more optional passenger detecting switch devices and the control circuit causes a shutter to conceal one or more of the taximeter's registers, in which the passenger detecting switch devices are effective, upon detecting the presence of a passenger, to render the control circuit effective to place the metering apparatus in a hired condition for registering a fare in the event that the driver fails to initiate operation of the meter upon accepting a passenger, in which the control circuit is switch operated for each hired setting to enable the driver to incrementally dispense a preset amount of free waiting time which is not charged to the passenger when the taxicab is held up by traffic or other conditions, and in which the clock or time drive of the meter is utilized to time the free waiting time period.

The diagram illustrates a three-terminal fuse assembly and its connection to a moveable contactor. The assembly (104) includes a housing (106) with three terminals labeled #1, #2, and #3. Terminals #1 and #2 are connected to a fuse (97) and a diode (267). The fuse is connected to a fuse terminal (235 8) and a diode terminal (267). The fuse assembly is connected to a moveable contactor (149) via terminals #1 and #2. Terminal #3 is connected to a terminal (221). The moveable contactor (149) is connected to a moveable contactor terminal (240) and a moveable contactor contact (237). The moveable contactor contact (237) is connected to a contact 237 terminal. The moveable contactor is also connected to a terminal (224) and a terminal (223).

PUSHBUTTON TAMPER PROOF TAXI-METER**FIELD OF INVENTION AND SUMMARY OF INVENTION**

The present invention relates to improvements in taximeters provided to register and display the fare to be charged for each hired operation of a taxicab equipped with the meter and to record, for end of day auditing operations by the driver and the operating facility's representatives, the pertinent data required to determine that proper returns are made to the operating facility and that proper operation of the taxicab according to the operating facility's rules and regulations has been effected. The present invention is directed to providing taximeters with adequate means to disclose unauthorized operation of the taxicab, tampering with the meter to effect an erroneous recording of the pertinent auditing data, simplified push button controls, means for selectively dispensing increments of a present amount of free waiting time, means to automatically sense the presence of an occupant other than the driver which will automatically initiate operation of the meter and pertinent signalling means when occupied by a passenger, and means to prevent undetected access to the interior of the installed meter.

The present invention is an improvement over the type of taximeter disclosed in U.S. Letters Pat. No. 2,596,164 issued to B.C. Palmer on May 13, 1962. Examples of other prior art are U.S. Letters Pat. Nos. 1,667,131 to F. Saurer; 1,675,046 to W.G. Arth et al.; 1,718,341 to C.A. Fauser et al.; 1,728,648 to A. Weiss; 1,850,741 and 1,873,539 to J.S. Brownell; 2,198,611 to J. Gardiner; 2,258,872 to J. Weisinger; 2,315,569 to White; 2,365,435 to R. Riegger; 2,411,273 to Kennedy et al.; 2,598,348 to O. Butler; 2,616,622 to Miller; 2,731,100 and 2,742,901 to O. Butler; 2,815,911 to G.M. McMuller; 2,934,159 and 3,111,185 to O. Butler; 3,157,352 to W.P. Caywood; 3,235,177 to W. Haupt et al.; 3,249,296 to H. Kelch; 3,254,833 to J.H. Condy et al.; 3,286,917 to H. Kelch; 3,325,097 to A. Slutsky; 3,343,624 to J. Shaheen; 3,501,092 to Mueller; 3,541,343 to O. Butler; 3,386,651 to S.H. Wallquist; 3,388,859 to H. Kelch et al.; 3,512,706 to J.F. Bruce-Sauders; 3,541,343 to O. Butler and 3,553,442 to E.S. Weisbart.

OBJECTS OF THE INVENTION

It is a primary object of the present invention to provide a taximeter wherein the operating mechanism and control circuitry is completely encased in a housing which, when installed in a taxicab, cannot surreptitiously be breached to falsify the recorded auditing data and a power supply cable is provided having a tamper circuit which, upon uncoupling of the power supply cable, will shutter the auditing data recorders rendering them inaccessible for reading to complete the end of day auditing check.

It is a further important object of the present invention to provide a taximeter with simplified push button controls for initiating operation of the meter and controlling its operation during "hired" setting of the meter to disrupt the time drive mechanism and provide a predetermined increment of "free waiting time" to the passenger during abnormal traffic conditions which prevent normal vehicular movement.

Another object of the present invention resides in the provision of a novel taximeter in which only a timed, preset amount of "free waiting time" can selectively be dispensed by the driver for each fare.

5 Still another object of the present invention is to provide the taximeter of any of the preceding objects with an occupant actuated starting circuit conditioned to operate after a predetermined timed interval to initiate normal operation of the meter in event the driver fails to initiate operation by actuating the push button controls.

A further object of this invention resides in providing a cam shaft controlled taximeter having a shiftable "mileage" drive gear train and a shiftable clock or 15 "time" drive gear train shiftable from a non-driving "for hire" position to a "hired" driving position with the meter drive shaft with reversible motor means drive connected to the cam shaft and driver actuated control circuitry including switch means selectively actuated by the driver to initiate forward rotation of the motor continued under the control of cam actuated switch means operable by respective cams on the cam shaft to terminate the initiated forward motor rotation at the normal "for hire" position of the cam shaft thereby 20 conditioning the meters for normal operation and further selective actuation of the switch means by the driver to initiate further forward rotation of the motor continued under control of the cam actuated switch means to terminate further forward motor rotation at a second "for hire" position of the cam shaft to maintain the display of the recorded fare accumulated when the driver, because of traffic conditions elects to condition the meter to either selectively effect disengagement of the clock or "time" drive gear train preparatory to dispensing the predetermined increment of "free waiting time" and then initiating reverse rotation of the motor and cam shaft to the normal "for hire" position to restore normal meter operation or alternatively wishes to stop the meter operation at the second 25 position to collect the registered fare and then initiate further forward rotation under control of the cam actuated switch means to the "for hire" position after collection of the accumulated recorded fare to reset the meter for the next trip.

BRIEF DESCRIPTION OF THE DRAWINGS

Further objects will appear from the following description and appended claims when read in conjunction with the accompanying drawings wherein:

50 FIG. 1 is a front elevational view of a taximeter of the present invention installed in the glove box compartment of a conventional taxicab;

FIG. 2 is a sectional view taken substantially on line 2-2 of FIG. 1 inside the right side frame assembly 55 looking in the direction of the arrows with certain of the conventional meter components omitted to illustrate the shiftable gear train of the clock drive gear train in its normal "for hire" position and the operating relay and "waiting time" switch associated therewith to provide the free waiting time feature of this invention;

60 FIG. 3 is a view of the left side frame assembly as viewed from the left of FIG. 1 with the cover and a portion of the gear box between the electric motor of the controls and the main control cam shaft broken away to better illustrate the two push button controls and printed circuit board employed to effect proper con-

nection of the electrical switches to secure selective operation of the meter in accord with this invention;

FIG. 4 is a front elevational view of the taximeter of this invention with the cover removed to better illustrate the major control switches and their cooperating actuating cams carried by the end of the conventional cam shaft of the taximeter;

FIG. 5 is a sectional view taken substantially on line 5-5 of FIG. 4 looking in the direction of the arrows to disclose the major control switches and their operating cams carried by the conventional cam shaft of this invention;

FIG. 6 is an elevational perspective view of the cam shaft of the taximeter of the present invention illustrating the several switch operating cams in their relative positions to the conventional cams provided to effect operative connection of the conventional mileage and time driven gear trains to the main drive shaft, the clock switch, and waiting time cutout switch provided by this invention and mounted between the right and left side frame assemblies shown in FIGS. 2 and 3;

FIG. 7 is an elevation view of the right side frame assembly as viewed from the right of FIG. 1 with the cover removed to better illustrate the tamper detection solenoid and its connection to the shutter means which are provided to thwart meter tampering by the driver and others (This figure also illustrates the waiting time disabling switch and a releasable mechanical solenoid latch in its unlatched condition);

FIG. 7A is a fragmentary elevation like FIG. 7, but showing the latched condition of the releasable mechanical solenoid latch;

FIG. 8 is a circuit diagram of the electrical control circuitry of the present invention;

FIG. 8A illustrates a jumper connection that is applied to the circuit of FIG. 8 when passenger detection is not desired; and

FIGS. 9, 10, 11 and 12 are partially schematic views of four of the control circuit cam-operated switches together with their switch-operating cams.

DESCRIPTION OF THE PREFERRED EMBODIMENT

With continued reference to the drawings wherein similar reference numerals are employed throughout the several views to indicate the same parts, the numeral 20 generally designates the push button taximeter of this invention. The taximeter 20 is composed principally of a meter base, cover and mechanical mileage and time drive components and fare and totalizing registers arranged and operating as shown and described in the aforesaid U.S. Letters Pat. No. 2,496,164 and controls generally designated 21 (see FIG. 8) provided by this invention to assure (1) that the meter will be properly used by the driver, (2) that the meter so used will at least partially compensate the passengers (the public) for traffic conditions which abnormally delay passage of the taxicab to its destination, and (3) that the meter will disclose to the operators any tampering or attempts to tamper with it to prevent its proper operation.

Referring for the moment to FIGS. 1 through 5, the meter framing comprises a support base 22 mounting in upstanding laterally spaced relation inwardly from its opposite ends a left side frame and drive gear and lever assembly 23 and a right side frame and extras drum and counter lever assembly 24 adapted to receive a remov-

able cover 25 having a top wall, depending sidewalls and a depending front wall having a window opening to be hereinafter described. As best seen in FIGS. 4 and 5, frame assemblies 23 and 24 are secured to upstanding mounting ears 26 integrally formed on the upper face of support base 22 by screws 27 which are enclosed by cover 25 when in place.

Support base 22 inwardly from side frame assembly 24 and the rear edge of support base 22 mounts a clock 10 assembly C and a clock driven gear and shear shaft assembly 29 (FIG. 2). Clock drive gear and shear shaft assembly 29 is journaled on one end of stub shaft 28 fixed to the frame plate 36 of side frame assembly 24 and supported at its other end in an upstanding arm of 15 clock assembly C.

The opposed frame plates 36 and 37 of assemblies 23 and 24 are through apertured at laterally, coaxially related points to support a register drum shaft assembly R; a combined fare drum transfer pinion frame and 20 clock stop finger shaft assembly 30; a cam shaft assembly 31; a drive shaft assembly 32 (See FIGS. 2, 5 and 7); a fare and trips counter lever shaft assembly 33 (FIGS. 3, 5 and 7) composed of respective stub journal shafts 34 and 35 fixedly secured to the side plates 36 25 and 37 of side frame assemblies 23, 24; a fare drum stop finger and tariff drum drive gear shaft assembly 38 (FIGS. 5 and 7). The construction and operation of assemblies R, 30, 32, 33, and 38 are substantially the same as that disclosed in the previously identified U.S. Pat. No. 2,596,164. So far as assemblies R, 30, 32, 33 and 38 are concerned, the only noteworthy variation is in assembly 33 where a single journal shaft of the patent extending between the side plates 36 and 37 has been replaced by the laterally aligned stub journal shafts 34 and 35, the latter journaling the fare registering lever assembly as described in the aforementioned Letters Patent. Except for certain significant additions to assembly 29, its construction is essentially the same as that disclosed in the previously identified U.S. Pat. No. 2,596,164. In accordance with one feature of this invention, assembly 30 has a special operating position for timing free waiting time as will be described in detail later on. Except for a number of significant additions, the construction of assembly 31 which is essentially the same as that disclosed in U.S. Pat. No. 2,596,164. So far as assembly 23 is concerned, the flag, the flag shaft and associated structure of the meter in U.S. Pat. No. 2,596,164 has been replaced by an electric motor and electrical controls which constitute part of this invention. The construction of assembly 24 corresponds to that disclosed in U.S. Pat. No. 2,596,164 except of the addition solenoid-controlled, tamper-detecting shutter mechanism of this invention. Thus, to the extent that the construction and operation of the meter disclosed herein is the same as that of the meter disclosed in U.S. Pat. No. 2,596,164, reference is made to U.S. Pat. No. 2,596,164.

Frame plates 36 and 37 at their front edges are spanned by a face plate 41 bolted to plates 36 and 37 at 42 and through apertured at 43 to define window openings at the left to expose the fare drums to view through the clear viewing areas panel 44 (FIG. 1) of cover 25 and a window opening at the right to expose a "Mode" (hired) drum 45 and an extras drum 46 to view through panel 44. Face plate 41 immediately above the window openings 43 is depressed inwardly to form a laterally coextensive, rearwardly offset groove

47 which is sufficiently deep to house a pair of panel illumination lights 48 (FIG. 4) and circuit wires to be presently described. At its upper edge, face plate 41 is notched at 49 to expose a "Total Mileage" indicator 51, at 52 to expose a "Paid Mileage" indicator 53 and a "Units" indicator 54, at 55 to expose a "Trips" indicator 56, and at 57 to expose an "Extras" indicator 58 to view through panel 44. These fare drums, "Mode" drum, "Extras" drum, "Total Mileage" indicator, "Paid Mileage" indicator, "Units" indicator, "Trips" indicator, and "Extras" indicator provide the information required to enable the driver and passenger to determine the fare to be paid to the driver and the accounting information to enable the driver to properly account to the owner-operator of the taxicab at the end of his day's run. The construction and operation of these drums and indicators is fully described in the aforementioned U.S. Letters Pat. 2,596,164 and will now be repeated here.

In a plane immediately above the notches 49, 52, 55 and 57, the side plates are through apertured at laterally aligned points to provide journals for the opposite ends of a small diameter shaft 59 integrally mounting respective "eyelid" type shutter flaps 61 and 62 normally disposed in their raised position above the respective notches as shown in FIG. 4. This normal positioning of shutters 61 and 62 is assured by fitting respective collars 63 and 64 to shaft 59 at the opposite sides of side plate 36 to establish the lateral positioning above the respective notches and by forming a radial recess or hole 65 in collar 64, to receive the upper end of retention plunger 66 of a tamper disclosure solenoid 67 to be hereinafter described. The uppermost front corners of side plates 36 and 37 are through drilled to receive screws 68 for securing the frame 69 mounting the digital counter wheels of the respective indicators 51, 53, 54, 56 and 58 in spanning relation between the side plates.

Referring for the moment to FIGS. 3 and 4, it will be noted that side plate 37 along its rear edge is provided with a pair of vertically spaced, outwardly protruding, integral ears 71. These ears journal the drive means 72 adapted to drivingly connect the mileage gear and lever mechanism 73 fully described in the aforementioned Letters Patent to the transmission of the taxicab as further pointed out in the aforementioned Letters Patent. Side plate 37 also mounts time delay mechanism 74 which cooperates with a portion of fare and trips counter levers shaft assembly 33 as fully described in the aforementioned Letters Patent to prevent movement of the registering lever of assembly 33 to its operating position until the initial fare registered on the meter has been consumed.

As best seen in FIG. 4, base 22 projects laterally well beyond sidewall 37 and a lesser distance laterally beyond side wall 36. The laterally projecting base beyond wall 37, formerly occupied by the flagshaft and its related structure in the aforementioned Letters Patent, is provided with an L-shaped bracket 81 the short leg 82 of which is bolted to base 22 by machine bolts 83 and the long leg 84 of which extends upwardly and angles rearwardly (FIG. 3) to support on its outer face a gear box 85 including an output gear 86 adapted to drive cam shaft assembly 31. The input gear 87 of gear box 85 is fixedly mounted on the end of a motor shaft 88 of an electric motor 89. Motor 89 is secured to the back face of gear box 85 by screws 91 (FIG. 3) passing

freely through passages (not shown) in the back face of gear box 85 into tapped passages 92 (FIG. 5) in the motor frame.

Motor 89 preferably comprises a light, low torque reversing motor driving from input gear 87 through a gear train including a series of compound gears 93, 94, 95 the latter of which includes a driving pinion gear 96 meshing with output gear 86 non-rotatably fixed to the shaft 97 of cam shaft assembly 31. While the rotational speed of shaft 97 is not critical, it is preferably sufficiently high to assure a rapid setting of the meter to its "Hired Time On" mode and to shift the meter from its "Hired Time On" mode to its "Hired Time Off" mode or its "For Hire" mode as described.

To effect energization of motor 89 and operation of taximeter 20, the present invention replaces the flag shaft actuator with a push button electrical control system schematically illustrated in FIG. 8 primarily controlled by driver actuation of spring loaded push button switches 101 and 102 (FIGS. 1 and 3) located at the left end of the front wall of cover 25 of the illustrated embodiment of the invention. It is to be understood, however, the push buttons 101 and 102 may be located in any convenient position on cover 25, for example the right end of the front wall should the meter be produced for use on a right hand drive taximeter or for mounting in the driver's compartment at a location to the left of the driver.

To adapt the meter of the aforementioned Letters Patent for push button operation, additional switch actuating cams are added to cam shaft assembly 31 to replace the flag shaft assembly shown in the aforementioned Letters Patent and cam actuated switches are mounted in juxtaposition to the added switching cams and electrically connected as hereinafter described to effect selective operation of the meter as will presently appear. Referring for the moment to FIGS. 3, 4, 5 and 6, the left protruding end of shaft 97 of cam shaft assembly 31 extends through the back wall of gear box 85 and fixedly mounts output gear 86 of the gear box drive gear train. Immediately adjacent the back wall of gear box 85 shaft 97 is fitted with a sleeve-like collar 103 non-rotatably fixed to shaft 97. The end of collar 103 nearest gear box 85 adjustably fixedly mounts a compound switch cam 104 (FIGS. 4, 5, and 6), an Allen set screw 105 (FIG. 4) providing for its angular and axial adjustment relative to collar 103. At its end opposing gear box 85 switch cam 104 is formed to provide a minor diameter arcuate cam surface 106 spanning approximately a 135° angle beginning clockwise at a 75° angle clockwise from the normal 12 o'clock rest position of shaft 97 and a major diameter arcuate cam surface 107. The ends of cam surfaces 106 and 107 are connected by inclined camming segments defining with cam surface 106 an included angle greater than 90° adapted to cooperate with the convex face 108 of the free end of a leaf spring switch actuator 109 of a cam operated meter "OFF-ON" switch 111 (FIGS. 4, 5 and 8). Switch 111 is fixedly mounted to the back face of leg 84 of bracket 81 below shaft 97 at an angle such that face 108 of actuator 109 contacts cam surface 106 midway of its length (See FIG. 5) to predetermine the normal meter "OFF" position or open position of switch 111 to be hereinafter described in detail.

The opposite end of switch cam 104 is formed to provide an annular cam surface 112 having a diameter equal to the minor diameter of cam surface 106. Cam

surface 112 is interrupted at three angular spaced intervals by triangular protrusions 113, 114, 115 (FIG. 5). Protrusion 113 is disposed 30° anticlockwise from the normal 12 o'clock position of shaft 97 (at the normal 11 o'clock position of shaft 97), protrusion 114 is disposed 90° anticlockwise from protrusion 113 (at the normal 8 o'clock position of shaft 97), the protrusion 115 is disposed 60° anticlockwise from protrusion 114 (at the normal 6 o'clock position of shaft 97) as will be clear from an inspection of FIG. 5. In the normal meter "OFF" or "For Hire" position of shaft 97, protrusion 113 is engaged by the rounded nose of a follower button 116 fixed to the free end of a leaf spring actuator 117 of a motor control switch 118 (FIGS. 5 and 8) to hold switch 118 open. Motor control switch 118 is fixedly mounted on the short leg 119 of an L-shaped bracket bolted to the back face of bracket 84 and will be presently described in detail.

The opposite end of collar 103 adjustably fixedly mounts a switch cam 121 (FIGS. 4 and 5), an Allen set screw 105 (FIG. 6) providing for its angular and axial adjustment relative to collar 103. Switch cam 121 is formed to provide a major diameter cam surface 122 interrupted by a minor diameter, arcuate cam surface 123 (FIGS. 4, 5 and 6) spanning approximately a 30° angle beginning 20° clockwise from the normal 12 o'clock rest position of shaft 97 and a protuberant formation 124 (FIGS. 5 and 6) at the normal 6 o'clock position of shaft 97. The ends of cam surfaces 122 and 123 are connected by inclined camming segments defining with cam surface 123 an included angle greater than 90°. In the normal meter "OFF" or "For Hire" position of shaft 97, protuberant formation 124 engages the rounded nose of a follower button 125 (FIG. 5) fixed to the free end of a leaf spring actuator 126 of a motor reversing switch 127 to maintain the switch open in the home or "for hire" position. Switch 127 fixedly mounts in piggy back relation an optional detection switch 128 (FIGS. 4, 5, and 8) carried by a support bracket 129. As will be clear from an inspection of FIG. 5, switch 128 includes a leaf spring actuator 130 having a round nosed follower button 131 normally abuttingly engaging the under free end of switch actuator 126 to close switch 128 in the home or "For Hire" position. As a consequence, the switch actuators 126 and 130 move in unison in response to the camming engagement of switch cam 121 with follower button 125 of switch actuator 126. The details and operation of switches 127 and 128 will be hereinafter described.

Referring now to FIG. 6, cam shaft 97 beginning immediately adjacent side plate 37 adjustably fixedly mounts mileage cam assembly 135; stop cam 136 adapted to cooperate with the fare registering lever assembly as fully described in the aforementioned U.S. Letters Pat. No. 2,596,164; transfer pinion frame actuating disc 137; stop finger operation cam 138; trips counter stop cam 139; tariff drum drive gear 141 fixedly mounting clock switch cam 142 and corresponding to the tariff drum drive gear of U.S. Letters Pat. No. 2,596,164; a trips counter stop cam 143 cooperating with the trips counter operating lever 144 operating as described in U.S. Letters Pat. No. 2,596,164; a combined clock stop finger and clock shear cam assembly 145 corresponding to and operating as described in detail in U.S. Letters Pat. No. 2,596,164 to control the clock drive gear and shear shaft assembly through clock shear 146; and a projecting end through

drilled at 147 to mount heart cam 148 (FIG. 7) operating as described in U.S. Letters Pat. No. 2,596,164. Since the construction and operation of the several cam shaft components, except for the switch cam 142 and the further clock switch 149 (FIGS. 6 and 8) mounted through bracket 151 on the support base 152 of clock assembly C to be hereinafter described, are fully described in aforementioned U.S. Letters Pat. No. 2,596,164, a detailed description thereof will be omitted here.

Support base 152 of clock assembly C comprises a main planar body portion 153 (FIG. 2) fixed to meter base 22 rearwardly of a vertical plane containing the axis of drive shaft assembly 32 and formed at its forward end with an upwardly offset support flange 154 to carry bracket 151. Rearwardly of flange 154 and along the edge nearest side frame assembly 36, support base 152 has an upstanding, planar, wall extension 155 mounting the clock drive motor 156, and the main clock drive gear train (not shown except for the primary or sun gear 161 journaled on stub shaft 28 and the cooperating shiftable gear train portion comprising meshingly engaging intermediate gears 162, 163 and final output gear 164 carried by clock shear 146). This main clock drive gear train and clock shear functions in exactly the same manner as that described in U.S. Letters Pat. No. 2,596,164 to time drive the meter drive shaft assembly 32 through one way drive gear 165 carried by shaft 166 of drive shaft assembly 32.

As will become apparent from further consideration of FIG. 2, the present invention provides the clock shear 146 with a depending arm 157 carrying a stub shaft 158 on its near face journaling at its inner end of a second output gear 159 meshingly engaging primary or sun gear 161 and normally disposed in non-meshing relation to a "free waiting time" drive gear 167 fixed on a stub shaft 168 journaled between its ends in side frame 36 and spring biased to a predetermined "home" position as will be presently explained. The opposite outer end of shaft 168 fixedly carries a switch cam 169 (FIG. 7) the purpose and operation of which will be presently described. Gears 164 and 159, by reason of their mountings on the respective arms of clock shear 146, are constantly driven by primary or sun gear 161 but are normally constrained by the positioning of clock shear 146 shown in FIG. 2 in the "home" or "for hire" position of the meter to assume a non-driving relationship with the respective mating gears 165 and 167 along respective clockwise directed arcuate paths having the axis of stub shaft 28 as a center.

As will be explained in greater detail later on, motor 89 is energized by selectively closing switch 101 to rotate cam shaft 97 from its illustrated "home" or "for hire" position to its "hired- waiting time on" or 3 o'clock position. Upon shifting of cam shaft 97 from its illustrated "home" position to the "hired" or 3 o'clock position, clock shear 146 shifts clockwise as seen in FIG. 2 to drivingly engage gear 164 with meter drive shaft gear 165, and the "mileage" shear 167 (FIG. 6) under control of mileage cam assembly 135 swings clockwise as seen in FIG. 6 to engage the mileage gear and lever mechanism 73 with the mileage drive gear (not shown) of drive shaft assembly 32 as fully described in U.S. Letters Pat. No. 2,596,164 thereby conditioning the meter for normal metering operation.

It will be appreciated from a consideration of FIG. 2, that shifting of clock shear 146 from its "home" or "for hire" position to "hired" position as just described swings gear 159 further away from its mating gear 167 thus necessitating counterclockwise movement of clock shear 146 beyond its illustrated "home" position (FIG. 2) to disengage gears 164 and 165 to interrupt the normal time drive and engage gear 159 with "free waiting time" drive gear 167. This movement is provided for by pivotally slot connecting the free terminal end of clock shear arm 157 to a drive pin 173 carried in the bifurcated end of the armature 174 (FIG. 2) of solenoid 175 mounted on a bracket 176 fixed to the inner face of side frame 36.

As will be described in greater detail shortly, solenoid 175 is energized upon rotation of cam shaft 97 from its "hired - waiting time on" or 3 o'clock position to its "hired - waiting time off" or 6 o'clock position. By selectively closing switch 101 again, motor 89 is energized to rotate cam shaft 97 from its 3 o'clock position to its 6 o'clock position.

As shown in FIG. 6, the leaf spring actuator 177 for switch 149 rides on the periphery of cam 142. When cam shaft 97 rotates to its 6 o'clock position, cam 142 will be positioned so that its notch or low part is opposite the follower formation on switch actuator 177, and actuator 177 will consequently ride into the notch or low part of cam 142. As a result, the movable contactor of switch 149 (See FIG. 8) will close switch contact 237 and will open switch contact 240.

Contact 240 is connected to the movable contactor of switch 178. Switch 178 has fixed contacts 274 and 274'. Contact 274 is connected through switch 172 to the ungrounded terminal of solenoid 175. Contact 274 also is connected through resistor 183 to the ungrounded terminal of solenoid 175. Resistor 183 and a solenoid 175 are connected in series between contact 274 and ground at 184. Switch 172 and solenoid 175 are also connected in series between contact 274 and ground. Switch 172 is in parallel with resistor 183 so that when it is closed it completes a shunt around resistor 183.

Through engagement with switch actuator 181, the high part or major diameter of cam 169 holds the movable contactor of switch 178 in engagement with contact 274.

Cam 179, which forms a part of the combined clock stop finger and clock shear cam assembly 145, will not shift clock shear 146 upon rotation with cam shaft 97 to its 6 o'clock position. Actuator 171 of switch 172 therefore will not be flexed to open switch 172. Thus, when cam shaft 97 reaches its 6 o'clock position to cause the movable contactor of switch 178 to close contact 274, switch 172 will be closed.

The engagement of the movable contactor of switch 178 with contact 274 will complete a circuit through switch 172 to energize solenoid 175 when cam shaft 97 is at its 6 o'clock position. This solenoid energizing circuit will be traced in greater detail later on.

As a result of energizing solenoid 175, armature 174 will move to the right as seen in FIG. 2 to swing clock shear 146 counterclockwise out of engagement with the actuating cam surface of cam 179 thereby engaging the clock drive gear 159 with gear 167 to effect rotation of gear 167 and shaft 168 clockwise as seen in FIG. 2. This counterclockwise displacement of clock shear 146 opens switch 172. Solenoid 175, however, will remain

energized through resistor 183. In advancing movement from its "home" position, shaft 97 also swings extra drum control cam 185 (FIG. 6) to shift detent lug 185' projecting from the face of cam 185 opposing side frame 85 clockwise to release spring biased anti-back-up pawl P (FIG. 2) to swing clockwise to ratcheting engage its long finger with the teeth of gear 167. This ratcheting engagement permits timed rotation of "free waiting time" shaft 168 and switch cam 169 carried thereby (counterclockwise as seen in FIG. 7). When the movable contactor of switch 178 closes contact 274 to complete the energizing circuit for solenoid 175, it also completes energizing circuits for illuminating a telltale light 186 and "time off" panel signal light 186' (FIGS. 1, 3 and 8). Lights 186 and 186' are connected in parallel between contact 274 and ground.

The timed rotated of shaft 168 and cam 169 will continue with cam shaft 97 in its 6 o'clock position until solenoid 175 is deenergized. Deenergization of solenoid 175 may be effected in either of two ways. First, the driver may selectively close push button switch 102 to cause reverse rotation of motor 89, thereby rotating cam shaft 87 counterclockwise (as viewed from FIG. 2) from its 6 o'clock position back to its "hired-waiting time on" 3 o'clock position. When cam shaft 97 arrives at its 3 o'clock position, cam 142 causes the movable contactor of switch 149 to open contact 240 and close contact 237. As a result, solenoid 175 will be deenergized. Secondly, deenergization of solenoid 175 may be effected by continued timed rotation of shaft 168 and cam 169 (about 108° in a typical installation set to dispense 2 minutes of "free waiting time") to position flat 190 of cam 169 opposite switch actuator 181, thereby causing the movable contactor of switch 178 to shift from its normal illustrated position of FIG. 8 to its alternate position where it engages contact 274. This operation of switch 178 will deenergize solenoid 175. Lights 186 and 186' will be extinguished when the movable contactor of switch 178 opens contact 274. Lights 186 and 186' will also be extinguished when the movable contactor of switch 149 disengages from contact 240. A circuit will be completed to illuminate the "time on" meter panel light 239 when the movable contactor of switch 149 closes contact 237 or when the movable contactor of switch 178 closes contact 274'.

Deenergization of solenoid 175 releases armature 174 allowing clock shear 146, due to its weight bias, to swing clockwise as seen in FIG. 2 to disengage gears 159 and 167 thereby disrupting the timed rotation of shaft 168 and cam 169 required to dispense "free waiting time." Since detent lug 185' (FIG. 2) in all operating positions of cam shaft 97 releases anti-back-up pawl P to enter between adjacent teeth of gear 167, gear 167, shaft 168 and cam 169 will be prevented from returning to their normal "home" position of FIG. 7 until cam shaft 97 is returned to its "home" position. As a consequence, "free waiting time" drive shaft 168 will remain in the position to which it has advanced ready to dispense any unused increment of "free waiting time" should be further traffic delay develop during the single hired trip until the meter push button switch 101 is normally driver actuated to advance cam shaft 97 to the 6 o'clock position to disconnect the time drive gear train and effect collection of the registered fare and then onward to the "home" position to clear the fare

register and reset the meter in its "for hire" position preparatory to being engaged by a second passenger. It will be understood that return of the meter to its "home" or "for hire" position will engage leg 185' of cam 185 with the short leg of anti-back-up pawl P to shift pawl P to its "home" position of FIG. 2 to disengage the long leg from gear 167. When thus disengaged, gear 167, shaft 168 and cam 169 will be 5 reversely rotated due to the stored energy in coil return spring 167' surrounding shaft 168 and connected at one end to spring anchor post p fixed to gear 167 and protruding toward side frame 36 and at its other end to post p' fixed to side frame 36 and projecting into the path of post p to engage the free end of post p and establish the "home" position of the "free waiting time" 15 shaft 168 and cam 169.

It will be appreciated from the preceding description of the "free waiting time" mechanism that dispensing of free waiting time is effected only at the option of the driver. It is also to be understood that the other control cams of cam shaft 97 are designed to maintain the operativeness of the mileage drive mechanism and the various fare registering and totalizing registers even when cam shaft 97 is in its 6 o'clock position to dispense "free waiting time." It follows, therefore, that the driver cannot, by advancing the cam shaft to its "free waiting time" position, cause the meter to operate defectively should he fail to restore the meter to its proper "hired - waiting time on" mode when traffic conditions permit normal movement of the taxicab. Furthermore, the total amount of "free waiting time" that can be dispensed each time the cam shaft 97 is shifted from its normal 3 o'clock hired position to its 6 o'clock "free waiting time" position is predetermined by the angular positioning of cam 169 on shaft 168. This is so since counterclockwise rotation of cam 169 beyond the point where the trailing edge of its major diameter cam surface intersects the flat 190 of cam 169 effects a release of actuator 181 permitting the spring biased actuator button of switch 178 to open switch 178, thereby deenergizing solenoid 175. Deenergization of solenoid 175 frees armature 174 to move to the left under the clockwise biasing force applied to clock shear 146 to reengage gears 164 and 165 conditioning the clock drive gear train to also drive the meter driveshaft assembly 31.

However, the driver can readily restore the meter to its normal operating or 3 o'clock (hired - waiting time on) mode any time that traffic permits him to proceed by actuating push button switch 102.

Referring for the moment to FIGS. 1, 3, 4, 7 and 8, relays RLA, RLB, meter panel lights 48, motor 89, switches 101, 102, 111, 118, 127, 128, 149, 172 and 178 together with their respective electrical circuits and the full meter control electrical circuitry shown in FIG. 8 is housed within cover 25 and base plate 22, and connections to the circuit in this enclosed space is provided by an armored supply cable 191 (FIGS. 3 and 7) connectible to the vehicle's electrical circuit through a well known Cinch-Jones connector plug and socket 192 (FIGS. 3 and 8). This arrangement assures that the driver or any other person who might wish to prevent proper operation and recording of the various registers cannot surreptitiously tamper with the meter or circuitry. To this end cover 25 is secured to base plate 22 by screws 193 (FIG. 2), preferably two at each side, extending upwardly through base plate 22 and threaded

into brackets 194 welded or otherwise fixedly secured to the sidewall inner faces of cover 25 together with mounting screws 195 entered upwardly through a mounting plate or glove box bottom wall 196 into threaded cap nuts 197 fitted into passages in base plate 22 and wired together in conventional fashion by sealed security wiring 198 (FIG. 2). Where desired, passenger detection circuit, which is generally indicated by numeral 199 (FIG. 8) and which includes seat and/or floor switches 210 (FIG. 8), is connected into the tamper proof circuitry so as to disclose any tampering with the passenger detection circuitry.

Referring for the moment to FIG. 2, it will be appreciated that plate or wall 196 covers the access holes in base plate 22 housing the heads of screws 193. As a consequence, removal of cover securing screws 193 can be effected only by severing sealed security wiring 198 and removing mounting screws 195 or by drilling the wall 196 at four points opposite the access holes to effect removal of screws 193. Gaining of access by either of these ways will, of course, be readily discernible by the checker employed by the owners to check in the drivers and collect the full fare shown by the meter to be due.

Referring next to FIGS. 3 and 8, it will be equally apparent that the housing of cable 191 enclosing the supply leads to the tamper proof electrical circuitry also encloses the supply leads to the passenger detection circuit 199 and that the end fitting 200 (FIG. 3) opening into the meter is a captive fitting secured internally in a passage in the back wall of cover 25. Any attempt to breach the housing of cable 191 to interrupt the supply lines to either the tamper proof electrical circuitry or the passenger detection circuitry 199 would likewise be discernible by the checker.

From the apparatus thus far described, it will be appreciated that cam shaft 197 is rotatable to three different operating positions by selective energization of motor 89. These three different operating positions are the home or "for hire" position (indicated as position No. 1 in FIGS. 9-12), the 3 o'clock, "hired - waiting time on" position (indicated as position No. 2 in FIGS. 9-12), and the 6 o'clock "hired - waiting time off" position (indicated as position No. 3 in FIGS. 9-12). Motor 89, as will be explained in detail shortly, is energized for forward rotation by selectively momentarily closing push button switch 101 and is energized for reverse rotation by selectively momentarily closing push button switch 102. Forward rotation of motor 89 rotates cam shaft 97 in a clockwise direction as viewed from FIG. 2, and reverse rotation of motor 89 rotates cam shaft 97 in a counterclockwise direction as viewed from FIG. 2. Switches 101 and 102 are spring biased to their normally open positions.

Thus, to rotate cam shaft 97 from its "for hire" position to its above-mentioned 3 o'clock position, switch 101 is momentarily selectively closed by the driver. To rotate cam shaft 97 from its 3 o'clock position to its above-mentioned 6 o'clock position, switch 101 is again selectively momentarily closed by the driver. To rotate cam shaft 97 from its 6 o'clock position back to its above-mentioned 3 o'clock position switch 102 is selectively momentarily closed by the driver. To rotate cam shaft 97 from its 6 o'clock position to its "home" or "for hire" position switch 101 is selectively momentarily closed by the driver.

When cam shaft 97 is advanced to its 3 o'clock hired position the meter fare computing mechanism will be controlled by the mileage drive and the clock or time drive to advance the fare register (indicated at 250a in FIG. 4) as described in the previously identified U.S. Pat. No. 2,596,164. More particularly, the clock drive has an output for advancing register 250a at a pre-selected rate which corresponds to a predetermined vehicle speed, and the mileage drive has an output for advancing register 250a at a variable rate which is in accord with the speed of the vehicle. In the 3 o'clock hired mode, register 250a will be driven at the faster one of these two rates so that if the vehicle is stopped or moving at a speed that is less than the above-mentioned predetermined rate, register 250a will be advanced at the above-mentioned pre-selected rate under the control of the clock drive. If the vehicle is moving faster than the above-mentioned predetermined speed, register 250a will be advanced at a rate that is in accord with the speed of the vehicle.

As previously explained, the clock drive in this embodiment is defined by clock 243, motor 156 and the previously described clock drive train components.

When cam shaft 97 is rotated to its 6 o'clock "hired-time off" position to provide for the energization of solenoid 175, the clock drive will be disengaged from the meter fare computing mechanism and therefore will be unable to advance fare register 250a as long as solenoid 175 remains energized. However, the mileage drive will still be operative to provide for the advancement of fare register 250a when cam shaft 97 is in its 6 o'clock position if the vehicle is placed in motion and has a speed that is equal to or greater than the above-mentioned predetermined speed.

Referring to FIG. 8, the external circuit connections for the circuit of this invention is provided by connector 192 which comprises a female socket 212 and a male plug 220.

Separate terminals in socket 212 are connected to conductors 213, 214, 215, 217, 208, and 209. Conductor 213 is connected to the positive 12 volt terminal of the vehicle's battery, conductor 214 is connected to the vehicle's headlight switch, conductor 215 is connected through a fuse 216 to the vehicle's ignition switch, conductor 217 is connected to the taxicab's roof top "for hire" signal light, and conductors 208 and 209 are connected to the passenger detecting seat and/or floor switches 210.

Separate terminals in plug 220 are connected to conductors 208', 209', 213', 214', 215', and 217'. Conductors 208', 209', 213', 214', 215', and 217' form the conductor core in cable 191. Selective connection of plug 220 to socket 212 connects leads 208, 209, 213, 214, 215, and 217 respectively to conductors 208', 209', 213', 214', 215', and 217'. Conductors 208', 209', 213', 214', 215', and 217' are respectively connected to separate terminals 228, 227, 221, 222, 223, and 214 on the printed circuit board 204.

From the foregoing it will be appreciated that terminal 221 is connected by connector 192 directly to the positive terminal of the vehicle battery so that a positive voltage (such as 12 volts, for example) is applied to terminal 221 with respect to ground. This potential will be applied to terminal 221 regardless of the condition of the vehicle's ignition switch.

The control circuit of FIG. 8 is provided with a polarity reversing relay RLA for motor 89. Relay RLA has

an operating winding 188 and three switches A₁, A₂ and A₃.

The solid line positions of switches A₁ and A₂ provide for current flow through the windings of motor 89 to drive motor 89 in its forward direction. When the movable contactors of switches A₁ and A₂ are transferred to the alternate dashed line positions in FIG. 8, the current flow through the windings of motor 89 is reversed to drive motor 89 in the reverse direction. Relay RLA is energized by closure of push button switch 102 in a manner to be described in detail later on.

As will be described in greater detail later on, relay RLB has a pair of switches B₁ and B₂ which are respectively connected in series with push button switches 101 and 102. The operating winding of relay RLB is indicated at 258. The purpose of switch B₁ is to interrupt the initial motor energizing circuit that is completed by closing switch 101 and to prevent indefinite energization of motor 89 by holding switch 101 closed. Similarly, the purpose of switch B₂ is to interrupt the initial motor energizing circuit that is established by closing switch 102, and it is also capable of preventing indefinite energization of motor 89 by holding switch 102 closed.

As shown in FIG. 8, terminal 221 is connected through fuse 203 to terminal 259 of the relay operating winding 258 and also to terminal 230 of operating winding 188. The ground side terminal of the relay operating winding 258 is indicated at 332 and is connected through a diode 260 and the normally open switch 118 to ground at 257.

Terminal 332 is also connected to the fixed contact 330 of switch B₁ and to the fixed contact 331 of switch B₂. The movable contactor of switch B₁ is connected to one contact of switch 101, and the other contact of switch 101 is connected to ground. The movable contactor of switch B₂ is connected through switch 127 to one contact of switch 102, and the other contact of switch 102 is connected to ground.

The ground side terminal of operating winding 188 is connected to the fixed contact 283 of switch A₃ and also to the fixed contact 328 of switch B₂. The fixed contact 322 of switch A₃ is connected to the fixed contact 323 of switch B₁.

The movable contactors of switches A₂ and A₃ are connected through diode 263 and switch 118 to ground. The movable contactor of switch A₁ is connected through fuse 203 to terminal 221. The fixed contact 320 of switch A₁ and the fixed contact 327 of switch A₂ are connected to one of the input terminals of motor 86, and the fixed contact 326 of switch A₁ and the fixed contact 321 are connected to the other input terminal of motor 89. A resistor 229 which is connected across the input terminals of motor 89 has one of its terminals connected to contact 326 and the other of its terminals connected to contact 327.

The switch and contact positions shown in FIG. 8 are for the "for hire" mode of the meter.

Assume that cam shaft 97 is in its "for hire" position and the driver desires to place the meter in its hired mode to register a passenger fare. To accomplish this, he selectively momentarily closes push button switch 101 to establish an initial energizing circuit for motor 89.

This initial energizing circuit may be traced from the positive terminal of the vehicle battery, through conductor 213, through connector 192, through conductor

213', through terminal 221, through fuse 203, through the movable contactor of switch A₁, through fixed contact 320 of switch A₁, through the winding circuit of motor 89, through the fixed contact 321 of switch A₂, through the movable contactor of switch A₂, through the fixed contact 322 of switch A₃, through the fixed contact 323 of switch B₁, through the movable contactor of switch B₁, and through switch 101 to ground. With this circuit it will be appreciated that one input terminal of motor 89 is always connected to the positive battery terminal through terminal 221 and connector 192.

When switch 101 is momentarily closed to complete the initial energizing circuit for driving motor 89 in the forward direction, cam shaft 97 will be advanced in a clockwise direction as viewed from FIG. 2. Upon initial rotation of cam shaft 97 in a clockwise direction, the protrusion 113 of cam 104 disengages from and moves away from the spring leaf actuator 117 of switch 118. As a result, switch 118 will close upon the initial clockwise rotation of cam shaft 97 from its "for hire" position towards its 3 o'clock "hired - waiting time on" position.

Closure of switch 118 provides a holding circuit for maintaining motor 89 energized to continue the rotation of cam shaft 97 towards its 3 o'clock "hired - waiting time on" position. This holding circuit may be traced from the positive terminal of the vehicle's battery, through connector 192 through terminal 221, through the movable contactor of switch A₁, through fixed contact 320, through the motor windings, through fixed contact 321, through the movable contactor of switch A₂, through diode 263 and through switch 118 to ground at 257.

Closure of switch 118 also completes the ground side of the energizing circuit for the relay RLB. This energizing circuit may be traced from the positive terminal of the vehicle's battery through connector 192, through terminal 221, through fuse 203, through the relay operating winding 258, through diode 260, and through switch 118 to ground. Energization of relay RLB therefore occurs upon the initial rotation of cam shaft 97 from its "for hire" position.

As a result of energizing relay RLB, the movable contactors of switches B₁ and B₂ will be transferred to the dashed line positions in FIG. 8. The movable contactor of B₁ will open the fixed contact 323 to interrupt or open the initial energizing motor circuit through push button switch 101.

At this stage, therefore, switch 101 may be opened, and motor 89 will remain energized through switch 118. As long as switch 118 remains closed, motor 89 will be energized to rotate cam shaft 97 in a clockwise direction as viewed from FIG. 2.

When cam shaft 97 reaches its 3 o'clock "hired - waiting time on" position the protrusion 114 of cam 104 engages the switch actuator 117 to open switch 118. Motor 89 will therefore be deenergized to stop rotation of cam shaft 97 at its 3 o'clock "hired - waiting time on" position.

Because of relay RLB, motor 89 will be deenergized by the opening of switch 118 to stop cam shaft 97 at its 3 o'clock position even though the driver does not release switch 101 and, instead, holds it closed.

If the driver holds switch 101 closed, relay RLB will not be deenergized upon the opening of switch 118

when cam shaft 97 reaches its 3 o'clock "hired - waiting time on" position. Instead, relay RLB will remain energized through switch B₁ and switch 101. This relay energizing circuit may be traced from the positive terminal of the vehicle's battery, through conductor 213, through connector 192, through conductor 213', through terminal 221, through the relay operating winding 258, through the fixed contact 330 of switch B₁, through the movable contactor of switch B₁ and through switch 101 to ground.

By holding relay RLB energized in this manner, the movable contactor of switch B₁ will be disengaged from contact 323, thereby preventing the continued energization of motor 89 through switch 101 after switch 118 opens. Thus, in order to continue the clockwise advancement of cam shaft 97 from its 3 o'clock hired position it is first necessary to release switch 101 and thereby deenergize relay RLB.

When switch 118 is opened by cam 104 at the 3 o'clock "hired - waiting time on" position of cam shaft 97 relay RLB will be deenergized if the driver has released switch 101 to its opened position.

It is desired to advance cam shaft 97 from its 3 o'clock "hired - waiting time on" position to its 6 o'clock "hired - waiting time off" position, switch 101, after being opened, is again selectively momentarily closed to complete the previously described initial energizing circuit through switches A₁, A₂, A₃, and B₁. This initial energization of motor 89 through switch 101 will again advance cam shaft 97 in a clockwise direction as viewed from FIG. 2.

The initial clockwise rotation of cam shaft 97 from its 3 o'clock hired position towards its 6 o'clock "hired - waiting time off" position moves cam protrusion 114 out of engagement with the switch actuator 117. As a result, switch 118 will again close to complete the previously described holding circuit for maintaining motor 89 energized through switches A₁, A₂. In addition, the closing of switch 118 will again energize relay RLB to thereby transfer the movable contactors of switches B₁ and B₂ to their illustrated dashed line positions in FIG. 8.

Thus, the movable contactor of switch B₁ will again open contact 323 to interrupt or open the initial motor energizing circuit that was established through the closure of switch 101. Switch 101 may now be released to its open position without causing deenergization of the motor 89, and motor 89 will remain energized through switch 118 to continue the rotation of cam shaft 97 towards its 6 o'clock "hired - waiting time off" position.

When cam shaft 97 reaches its 6 o'clock "hired - waiting time off" position, cam protrusion 115 engages the switch actuator 117 to open switch 118. Motor 89 will therefore be deenergized to stop rotation of cam shaft 97 at its 6 o'clock "hired - waiting time off" position. In addition, the opening of switch 118 will deenergize relay RLB if switch 101 is open, thus transferring the movable contactors of switches B₁ and B₂ to their illustrated full line positions in FIG. 8.

From the foregoing it will be appreciated that switch 118 is open whenever any one of the cam protrusions 113, 114, or 115 engages the actuator 117 of switch 118. Thus, whenever cam shaft 97 is at any one of its three operative positions (namely its "for hire" position, its 3 o'clock "hired - waiting time on" position, and its 6 o'clock "hired - waiting time off" position) switch

118 will be open. For all other positions of cam shaft 97, switch 118 will be closed. The ohmic value of resistor 229 is made small enough so that it acts as a brake for motor 89 when power is removed from the motor to assure that cam shaft 97 does not overrun any of its for-hire or hired positions.

At the 6 o'clock "hired-waiting time off" position of cam shaft 97, cam 121 will be in such a position that the follower on the actuator 126 of switch 127 seats in the low part (surface 123) of cam 121. As a result, switch 127 will close when cam shaft 97 is rotated to its 6 o'clock "hired waiting time off" position. For all other positions of cam shaft 97, switch 127 will be open. More specifically, when cam shaft 97 is in its "for hire" position the follower on switch actuator 126 engages protrusion 124 to thus hold switch 127 open. Switch 127 will remain open as long as the follower on switch actuator 126 engages the high part or surface 122 of cam 121.

By closing switch 127 at the 6 o'clock position of cam shaft 97, the circuit is conditioned to energize motor 89 with reverse polarity by momentarily closing switch 102. Therefore, if it is desired to rotate cam shaft 97 in a counterclockwise direction (as viewed from FIG. 2) back to its 3 o'clock "hired-waiting time on" position, the driver momentarily closes switch 102 to complete a circuit for energizing the relay operating winding 188. This relay energizing circuit may be traced from the positive terminal of the vehicle's battery, through conductor 213, through connector 192, through conductor 213', through terminal 221, through operating winding 188, through switch B₂, through switch 127, and through switch 102 to ground. Energization of relay operating winding 188 transfers the movable contactors of switches A₁, A₂, and A₃ to the dashed line positions shown in FIG. 8.

By transferring the movable contactors of switches A₁ and A₂ to the dashed line positions shown in FIG. 8, the energizing circuit for reversely rotating motor 189 is completed and may be traced from the positive terminal of the vehicle's battery, through conductor 213, through connector 192, through conductor 213', through terminal 221, through the movable contactor of switch A₁, through the fixed contact 326 of switch A₁, through the motor windings, through the fixed contact 327 of switch A₂, through the movable contactor of switch A₂, through the movable contactor of switch A₃, through the fixed contact 283 of switch A₃, through the fixed contact 328 of switch B₂, through the movable contactor of switch B₂, through switch 127, and through switch 102 to ground. With these circuit connections it will be appreciated that switch A₁, the windings of motor 89, switch A₂, switch A₃, switch B₂, switch 127, and switch 102 are in series between the positive battery terminal and ground.

Motor 89 will therefore be energized in a reverse direction to rotate cam shaft 97 in a counterclockwise direction as viewed from FIG. 2.

The initial rotation of cam shaft 97 in a counterclockwise direction from its 6 o'clock "hired - waiting time off" position causes the protrusion 115 of cam 104 to move out of engagement with the actuator 117 of switch 118. As a result, switch 118 will close upon the initial counterclockwise rotation of cam shaft 97 from its 6 o'clock position.

Closure of switch 118 will again complete a holding circuit for maintaining motor 89 energized so that

switch 102 may be released to its open position without causing deenergization of the motor. This motor holding circuit may be traced from the positive terminal of the vehicle's battery, through conductor 213, through connector 192, through conductor 213', through terminal 221, through the movable contacts of switch A₁, through fixed contact 326, through the windings of motor 89, through fixed contact 327, through the movable contactor of switch A₂, through diode 263, and through switch 118 to ground.

Closure of switch 118 energizes relay RLB as previously described. As a result, the movable contactors of switches B₁ and B₂ will be transferred to the dashed line positions shown in FIG. 8.

Transfer of the movable contactor of switch B₂ to the dashed line position shown in FIG. 8 interrupts or opens the initial circuit that was established through the closure of switch 102 for energizing relay operating winding 188. Relay operating winding 188, however, will now be maintained energized through switches A₃ and 118. This relay holding circuit may be traced from the positive battery terminal, through conductor 213, through connector 192, through conductor 213', through terminal 221, through relay operating winding 188, through fixed contact 283, through the movable contactor of switch A₃, through diode 263, and through switch 118 to ground. Thus, motor 89 will continue to be energized for rotating cam shaft 97 in a counterclockwise direction as viewed from FIG. 2.

Switch 127 will open shortly after relay RLB is energized and upon initial counterclockwise rotation of cam 121 with cam shaft 97. Motor 89 will continue to rotate cam shaft 97 in the counterclockwise direction as viewed from FIG. 2 until cam shaft 97 reaches its 3 o'clock "hired - waiting time on" position.

When cam shaft 97 is returned to its 3 o'clock position, cam protrusion 114 engages the follower on the switch actuator 117 of switch 118. As a result, switch 118 will open to deenergize motor 189 and to thereby stop rotation of cam shaft 97 at its 3 o'clock "hired - waiting time on" position. At this stage, motor 89 cannot again be reversely energized to rotate cam shaft 97 in a counterclockwise direction because switch 127 is now open.

Furthermore, a circuit for energizing motor 89 cannot be completed through switch 102 as long as relay RLB remains energized.

Because of the operation of switch 127, motor 89 can be reversely energized by closing switch 102 only when cam shaft 97 is in its 6 o'clock "hired - waiting time off" position. When cam shaft 97 is in its 3 o'clock "hired - waiting time on" position switch 127 will be open, thereby preventing the completion of a circuit for energizing either relay RLA or motor 189. Also, switch 127 will be open in the "for hire" position of cam shaft 97 to thereby prevent a circuit from being completed through switch 102 for energizing either motor 89 or relay RLA. Thus, for all positions of cam shaft 97 except its above-mentioned 6 o'clock position closure of switch 102 will not result in energization of motor 89.

If it is desired to return cam shaft 97 to its "for hire" position when the cam shaft is in its 3 o'clock "hired - waiting time on" position, it is necessary for the driver to first advance cam shaft 97 clockwise (as viewed from FIG. 2) by momentarily selectively closing switch 101 and then to advance cam shaft 97 clockwise from

its 6 o'clock position to its home or "for hire" position by again momentarily closing switch 101.

The initial momentary closure of switch 101 energizes motor 89 for rotation in a forward direction to cause cam shaft 97 to be rotated clockwise to its 6 o'clock "hired - waiting time off" position as previously described. When cam shaft 97 reaches this 6 o'clock position motor 89 will be deenergized even though the driver holds switch 101 closed for the reasons previously mentioned.

Upon reaching the 6 o'clock "hired - waiting time off" position the driver then must momentarily re-close switch 101 to again energize motor 89 for rotation in a forward direction. Cam shaft 97 will again rotate clockwise as viewed from FIG. 2. The initial clockwise advancement of cam shaft 97 causes cam protrusion 115 to move away from the follower on switch actuator 117. As a result, switch 118 will close upon initial clockwise rotation of cam shaft 97 from its 6 o'clock "hired - waiting time off" position. Closure of switch 118 completes the previously described holding circuit for maintaining motor 89 energized in its forward direction. Closure of switch 118 also energizes relay RLB, thereby transferring the movable contactors of switches B₁ and B₂ to the dashed line positions shown in FIG. 8. Shortly after relay RLB is energized, switch 127 will open because of the engagement of cam surface 122 with the follower on switch actuation 126.

When cam shaft 97 reaches its home or "for hire" position, cam protrusion 113 will again engage the follower of switch actuation 117 thereby opening switch 118. By opening switch 118, motor 89 will be deenergized to stop cam shaft 97 at its "for hire" position. Also, the opening of switch 118 deenergizes relay RLB.

Diode 260 prevents motor current from bypassing switch 118 if switch 101 is held closed. Diodes 263a and 263b, which are respectively in parallel with relay windings 188 and 258, are arc suppressors to provide contact protection for the inductive energy in windings 188 and 258.

As shown in FIG. 8, the cam operated switch 111 has a set of normally closed contacts 246 and 247 and a set of normally open contacts 232 and 233. When cam shaft 97 is in its home or "for hire" position, the movable contactor of switch 111 engages cam surface 106. The movable contactor of switch 111 will therefore be in its illustrated position to close contacts 246 and 247. In this position the normally open contacts 232 and 233 are open. When cam shaft 97 is either in its above-mentioned 3 o'clock position or its above-mentioned 6 o'clock position, the movable contactor of switch 111 engages cam surface 107. The movable contactor of switch 111 will therefore be transferred to close the normally open contacts 232 and 233 and to open normally closed contacts 246 and 247.

Still referring to FIG. 8, contact 246 is connected directly to terminal 223. Contact 247 is connected to terminal 224 and also through a telltale light 249 to ground at 22. Thus, when the vehicle ignition switch is turned on and when cam shaft 97 is in its "for hire" position, the roof top for hire light of the taxicab and light 249 will be illuminated.

The circuit for illuminating light 249 may be traced from the vehicle's battery through the vehicle's ignition switch, through conductor 215, through connector 192, through conductor 215', through switch 111, and

through light 249 to ground. The circuit for energizing the roof top for hire light may be traced from the vehicle's battery, through the vehicle's ignition switch through conductor 215, through connector 192, through conductor 215', through switch 111, through conductor 217', through connector 192, through conductor 217, through the roof top for hire light to ground.

As shown in FIG. 8, contact 232 is connected directly to terminal 221 so that a 12 volt potential is always applied to contact 232 with respect to ground.

When the movable contactor of switch 111 is transferred to its alternate position to open the circuit between contacts 246 and 247, light 249 and the taxicab's roof top light will be extinguished.

Contact 233 is connected through a diode 267 and through a fuse 277 to corresponding terminals of indicator panel lamps 272. The ground side terminals of lamps 272 are connected to ground at 273. Lamps 272 are connected in parallel between ground and fuse 277. Thus, each lamp, fuse 277 and diode 267 are connected in series between ground and contact switch,

In addition, terminal 222 is connected through a further diode 268 and through fuse 277 to the positive potential terminals of lamps 272. Thus, each lamp 272, fuse 277 and diode 267 are connected in series between ground and terminal 222 to provide the energizing circuit for illuminating lamps 272 by operation of the vehicle's headlight switch. One terminal of fuse 277 is connected to the positive potential terminals of lamps 272 and the other terminal of fuse 277 is connected to the cathodes of diodes 267 and 268.

From the foregoing it will be appreciated that lamps 272 may be illuminated either by closing the vehicle headlight switch (which illuminates the unshown headlights of the vehicle) or by actuating switch 111 to close contacts 232 and 233. One circuit for illuminating lamps 272 may be traced from the vehicle's battery, through the vehicle's headlight switch, through conductor 314, through connector 192, through conductor 214', through terminal 222, through diode 268, through fuse 277 and through lamps 272 to ground.

When the movable contactor of switch 111 is transferred to its alternate position to close the circuit between contacts 232 and 233, lamps 272 will be illuminated through the circuit that may be traced from the positive terminal of the vehicle's battery, through conductor 231, through connector 192, through conductor 213', through terminal 221, through contact 232, through the movable contactor of switch 111, through contact 233, through diode 267, through fuse 277 and through lamps 272 to ground. Even though the vehicle's head-light switch is open, lamps 272 will therefore be illuminated whenever cam shaft 97 is in either its above-mentioned 3 o'clock position or its above-mentioned 6 o'clock position to thereby provide a signal that the taxicab is hired.

From the foregoing it will be appreciated that the vehicle headlight switch and switch 111 are in parallel between the vehicle's battery and the lamps 272 so that actuation of either will illuminate lamps 272.

Diode 267 prevents energization of solenoid 175 and a clock 243 by the current that is supplied through diode 268 when the vehicle headlight switch is closed.

As shown in FIG. 8, switch contact 233 is also connected through fuse 235 to the movable contactor of

switch 149 and to the input of clock 243. More specifically, one terminal of fuse 235 is connected to contact 233 and also to the anode of diode 267. The other terminal of fuse 235 is connected to the movable contactor of switch 149 and to the input of clock 243.

The output of clock 243 is connected to the windings 243 of clock drive motor 156 as shown. Clock 243 may be any suitable, conventional power supply circuit for driving motor 156 at a substantially constant, pre-selected speed. For example, clock 243 may comprise a suitable oscillator for generating a square wave having pulses of constant, pre-selected frequency. Clock 243 is connected between contact 233 and ground so that when contacts 232 and 233 are closed a positive potential will be applied to the circuit of clock 243 to thereby energize the clock circuit. Energization of the circuit of clock 243 energizes motor 156.

From the circuit thus far described, it will be appreciated that the circuit of clock 243 and hence motor 156 will be deenergized when cam shaft 97 is in its home or "for hire" position because contacts 232 and 233 will be open in this position of the cam shaft. When cam shaft 97 is rotated to either its previously mentioned 3 o'clock position or to its previously mentioned 6 o'clock position, the movable contactor of switch 111 will be transferred to close the circuit between contacts 232 and 233, thereby completing a circuit to energize clock 243.

Thus, motor 156 will be energized when cam shaft 97 is in either its previously mentioned 3 o'clock position or its previously mentioned 6 o'clock position. Motor 156 will be deenergized when cam shaft 97 is in its home or "for hire" position.

The circuit for energizing clock 243 may be traced from the positive terminal of the vehicle's battery, through conductor 213, through connector 192, through conductor 213', through terminal 221, through contact 232, through the movable contactor of switch 111, through contact 233, through fuse 235, and through clock 243 to ground.

Although the movable contactor of switch 149 closes contact 240 and the movable contactor of switch 178 closes contact 274 when the meter is in its "for hire" mode, solenoid 175 will not be energized because contacts 232 and 233 are open. When cam shaft 97 is advanced to its 3 o'clock "hired-waiting time on" position, switch 111 will be actuated to close contacts 232 and 233, but the energizing circuit for solenoid 175 still will not be completed because advancement of cam shaft 97 to its above-mentioned 3 o'clock position transfers the movable contactor of switch 149 so that it opens contact 240.

In order to energize solenoid 175, the movable contactors of switches 149 and 178 must be in the positions illustrated in FIG. 8 and the movable contactor of switch 111 must be transferred to close the circuit between contacts 232 and 233. As previously mentioned, switch 111 is actuated by cam 104 to close contacts 232 and 233 only when the cam shaft 97 is advanced to either its above-mentioned 3 o'clock position or its above-mentioned 6 o'clock position. When cam shaft 97 is in its 3 o'clock position the movable contactor of switch 149 will be transferred to close contact 237 and to open contact 240. When cam shaft 97 is transferred to its above-mentioned 6 o'clock position, the movable contactor of switch 149 is transferred back to its illustrated position to close contact 240. The movable con-

tactor of switch 178 will remain in contact with contact 274 as long as it engages the high part or the major diameter cam surface of cam 169 to thereby indicate that "free waiting time" is still available.

5 From the foregoing it will be appreciated that solenoid 175 can only be energized when cam shaft 97 is in its above-mentioned 6 o'clock position and when "free waiting time" is still available. Therefore, the 10 clock drive can only be driven connected to shaft 168 when cam shaft 97 is in its above-mentioned 6 o'clock position and when "free waiting time" is still available.

The circuit for energizing solenoid 175 may be traced from the positive terminal of the vehicle's battery, 15 through conductor 213, through connector 192, through conductor 213', through terminal 221, through contact 232, through the movable contactor of switch 111, through contact 233, through fuse 235, through the movable contactor of switch 149, through contact 240, through the movable contactor of switch 178, through contact 274, through switch 172, and through solenoid 175 to ground. Switch 172, as previously explained, will be closed when clock shear 146 is in the position shown in FIG. 2. Clock shear 146 will 25 be in this illustrated position when solenoid 175 is de-energized.

Energization of solenoid 175 swings clock shear 146 in a counterclockwise direction as viewed from FIG. 2 to thereby open switch 172. Solenoid 175, however, 30 will be maintained energized through resistor 183 which was originally shunted by contacts 172 when they were closed. Contacts 172 shunt resistor 183 to initially apply a relatively high voltage to energize solenoid 175.

35 From the foregoing solenoid energizing circuit it will be appreciated that solenoid 175 will be deenergized when the timed rotation of shaft 168 has moved cam 169 to a position where the cam flat 190 is opposite the switch actuator 181, thereby indicating that the total 40 available "free waiting time" has been dispensed for a particular fare. As a result, the movable contactor of switch 178 will open contact 274 and will close contact 274'. Solenoid 175 will consequently be deenergized as previously explained.

45 If cam shaft 97 is rotated back to its above-mentioned 3 o'clock position before all of the "free waiting time" is dispensed, the movable contactor of switch 149 will open contact 240 and will close contact 237. This switch operation will also deenergize solenoid 175. If "free waiting time" is still available and if cam shaft 97 is advanced from its 6 o'clock position to its home or "for hire" position, switch 111, under the action of cam 104, will open contacts 232 and 233 to thereby deenergize solenoid 175.

50 Deenergization of solenoid 175 releases clock shear 146 to re-establish the clock drive as previously described if cam shaft 97 is in its 3 o'clock, hired position.

60 When cam shaft 97 is in its above-mentioned 6 o'clock position, light 239 will be illuminated through a circuit that may be traced from the positive terminal of the vehicle's battery, through conductor 213, through connector 192, through conductor 213', through terminal 221, through switch 111, and through the filament of the light to ground. If all of the "free waiting time" is dispensed and cam shaft 97 is still in its 6 o'clock position, light 239 will be illuminated through

switch 111, through the movable contactor of switch 149, through contact 240, through the movable contactor of switch 178, through contact 274' and through the filament of the light to ground. When solenoid 175 is energized, lights 186 and 186' will be energized through switches 111, 149 and 178.

In operation of the meter thus far described it will be appreciated that when cam shaft 97 is in its "for hire" position, the roof top "for hire" light and the "for hire" panel light 249 will be illuminated when the ignition switch of the vehicle is turned on. In the "for hire" mode of the meter, a cam and a lever assembly (not shown), which is fixed to drum 45 and which is fully described in the previously identified U.S. Pat. No. 2,596,164, operates to position the "for hire" shutter 250 to its uppermost position to cover the fare register as shown in FIG. 1. With cam shaft 97 in its "for hire" position, motors 89 and 156 and solenoid 175 will be deenergized.

When the driver accepts a passenger, he momentarily closes push button switch 101 to effect the advancement of cam shaft 97 to its 3 o'clock "hired - waiting time on" position. As a result, the "for hire" shutter 250 will be released by drum 45 for downward movement to expose the fare register drums, "mode" drum 45, and the extras drum 46, which are viewable through windows 43 (See FIG. 4). In addition, switch 111 will be actuated to open contacts 246 and 247 and to close contacts 232 and 233. Thus, the roof top "for hire" light and the "for hire" panel light 249 will be extinguished. Now, however, the "time on" metal panel light 249 will be illuminated through switches 111 and 149.

Upon advancement of cam shaft 97 to its 3 o'clock position, the time drive motor 156 will be energized as previously explained. In addition, the cam shaft mechanism control cams, namely, the cam control mileage cam assembly 135, stop cam 136 which controls the fare registering lever assembly, the transfer pinion frame actuating disc 137, the stop finger operating cam 138, the trips counter stop cam 139 which controls the trips counter tariff drum drive gear 141, the trips counter stop cam 143 which controls the trips counter operating lever 144, the cam controlling combined clock stop finger and clock shear cam assembly 145 which controls clock shear 146, and the heart cam 148 will be positioned to effect registering operation of the meter mechanism as fully described in the previously identified U.S. Pat. No. 2,596,164. As a result, the meter will be fully conditioned in its 3 o'clock operation position to effect both mileage and clock timed driving of the meter drive shaft assembly 32.

If, in the course of proceeding to the passenger's destination, traffic or other conditions are encountered that require the driver to stop the taxicab, the driver may permit the meter to continue running by leaving the meter in its 3 o'clock "hired-waiting time on" mode. Under these conditions, the clock or time drive motor 156 will advance fare register 250a as previously explained.

Alternatively, the driver may elect to dispense "free waiting time" by momentarily closing switch 101 to effect the advancement of cam shaft 97 to its above-mentioned 6 o'clock position. In this operating mode of the meter, the fare register 250a will not be advanced by the clock drive motor 156, and no additional fare will be registered by the fare drums as long as the vehi-

cle is not moving. As a result, the passenger will not be charged with additional fare until the driver momentarily closes switch 102 to effectuate the return of cam shaft 97 to its above-mentioned 3 o'clock position or until the total available "free waiting time" period is consumed to cause deenergization of solenoid 175.

Upon advancing cam shaft 97 from its above-mentioned 3 o'clock position to its above-mentioned 6 o'clock position to dispense available "free waiting time", the "time on" meter panel light 239 will be extinguished, the "time off" roof top light 186 will be illuminated, the "time off" panel signal light 186' will be illuminated, and solenoid 175 will be energized.

Energization of solenoid 175 retracts armature 174, thus causing the clock drive gear and shear shaft assembly 29 (See FIG. 2) to swing counterclockwise beyond its FIG. 2 position to disengage gears 164 and 165 and to engage gear 159 with the "free waiting time" drive gear 167. This counterclockwise rotation of the clock shear 146 will open switch 172, and solenoid 175 will remain energized through resistor 183.

From the foregoing it will be appreciated that the normal clock drive gear train to the meter drive shaft assembly 32 is disrupted and that the clock drive will advance movement of the "free waiting time" shaft 168 and its associated switch-operating cam 169 counterclockwise as seen from FIG. 7. This rotation of shaft 168 and cam 169 continues as long as solenoid 175 remains energized. In the 6 o'clock position of cam shaft 97 the mileage gear and lever mechanism 73 is still drivingly coupled to the meter drive shaft assembly 32 to effect mileage drive of drive shaft assembly 32 should the driver initiate movement of the taxicab without disrupting the driving connection of the clock motor to the "free waiting time" shaft 168.

In proper usage of the meter, the driver terminates the dispensing of the "free waiting time" by selectively momentarily closing push button switch 102 when the traffic or other conditions permit him to continue towards the passenger's destination. As previously explained, momentary closure of switch 102 effectuates the return of cam shaft 97 to its 3 o'clock "hired-waiting time on" position to thereby restore normal meter operation. Any unconsumed time in the total available free waiting period will consequently be reserved.

With cam shaft 97 back at its 3 o'clock "hired-waiting time on" position, normal operation of the meter is resumed to provide time responsive, as well as mileage responsive, fare registration by fare register 250a.

Upon the return of cam shaft 97 to its above-mentioned 3 o'clock position, the assembly of shaft 168 and switch-operating cam 169 is held in the position to which it was advanced at the time that push button switch 102 was momentarily closed because the engagement of the spring biased anti-back-up pawl P with the teeth of gear 167 (See FIG. 5) arrests reverse rotation of shaft 168 by return spring 167' (See FIG. 2).

From the foregoing it will be appreciated that driver actuation of push button switch 101 to effect advancement of cam shaft 97 to its above-mentioned 6 o'clock position can repeatedly be effected to dispense "free waiting time" in selected time increments until the preset 2 minute maximum, which is allowed by the timed rotation of shaft 168, is used up. Thus, the driver may optionally dispense "free waiting time" at one or more

different intervals until the total amount of the preset "free waiting time" is consumed.

Termination of "free waiting time" is effected when the timed rotation of shaft 168 by motor 156 positions cam flat 190 opposite switch actuator 181. In this position of cam flat 190, the movable contactor of switch 178 will be transferred to open contact 274 and to close contact 274'. As a result, solenoid 175 will be de-energized, lights 186 and 186' will be extinguished, and light 239 will be illuminated.

Illumination of light 239 signals the driver that all of the "free waiting time" has been dispensed. Upon using up the total available preset, "free waiting time" for a given fare, no additional "free waiting time" can be dispensed until the meter is reset to its "for hire" mode and is subsequently placed in its operative hired mode for registering a new fare.

Upon using up the total available "free waiting time" for a given fare, subsequent advance of cam shaft 97 to its above-mentioned 6 o'clock position will not be effective to cause energization of solenoid 175 because the movable contactor of switch 178 will be held out of engagement with contact 274 by cam 169.

Should the driver momentarily close switch 101 to again effect the advancement of cam shaft 97 to its above-mentioned 6 o'clock position after all of the "free waiting time" has been dispensed, clock shear 146 will not be rotated to disengage gears 164 and 165 because solenoid 175 will not be energized. Thus, clock drive motor 156 will remain drive connected to cam shaft assembly 32 to provide for fare registration.

Assume that there is still some "free waiting time" available when the taxicab reaches the passenger's destination, and that upon reaching the destination, cam shaft 97 is in its 3 o'clock "hired - waiting time on" position. Under these conditions the driver may momentarily close switch 101 to effect advancement of cam shaft 97 to its 6 o'clock "hired - waiting time off" position, thereby eliminating the registration of a fare while he is collecting the fare from the passenger.

After the driver has collected the fare from the passenger, he then momentarily closes switch 101 to effect advancement of cam shaft 97 from its above-mentioned 6 o'clock position to its home or "for hire" position in preparation for receiving another fare.

In the event that the total available "free waiting time" has been consumed when the taxicab reaches the passenger's destination, the driver upon reading the registered fare to be paid by the passenger, momentarily closes switch 101 to effect advancement of cam shaft 97 to its above-mentioned 6 o'clock position and then immediately re-closes switch 101 to effect advancement of cam shaft 97 to its home or "for hire" position.

Upon returning cam shaft 97 to its home or "for hire" position, switch 111 will be actuated to open contacts 232 and 233 and to close contacts 246 and 247. As a result, the roof top for hire light and the "for hire" panel signal light 249 will be illuminated, and clock 243 will be deenergized. The opening of contacts 232 and 233 prevent illumination of light 239. In addition, the various mechanism control cams will be returned to their "home" positions to reset the meter mechanism as fully described in the previously identified U.S. Pat. No. 2,596,164, thereby conditioning the meter mechanism for its next metering operation.

As an incident to the resetting of the meter mechanism, detent lug 185' (FIG. 2) which is carried by extra drum control cam 185 (FIG. 6), will move clockwise (FIG. 2) to engage the short leg of spring biased anti-back-up pawl P and swing the pawl counterclockwise around its pivot axis to disengage the long arm of pawl P from the teeth of the "free waiting time" driven gear 167. Disengagement of pawl P frees gear 167 and free waiting time drive shaft 168 and its associated switch cam 169 to be returned to their "home" positions as determined by engagement of spring anchor posts p and p' under the biasing force of return spring 167'. Homing of shaft 168 and switch cam 169 engages the peripheral arcuate cam surface of cam 169 with actuator 181 to shift and hold the spring biased button actuator of timed switch 178 closed to contact 274, thereby re-conditioning the meter to again dispense the full preset increment of "free waiting time".

As a further incident of the resetting of the meter mechanism, the cam of combined clock stop finger and clock shear cam assembly 145 engages the clock shear 146 to position the clock drive gear and shear shaft assembly 29 in its "home" position (FIG. 2) with both sets of gears, gears 159, 167 and gears 164, 165, disengaged. Since this "home" position places the free end of clock shear 146 in slightly counterclockwise shifted position from its normal operating position with gears 164 and 165 engaged, and switch 172 is adjustably mounted on side frame plate 36 to assure that switch 172 will be mounted to assume its normally closed position as shown in FIG. 8 until clock drive gear and shear shaft assembly 29 reaches a position to mesh gear 159 with gear 167.

As shown in FIG. 8, the terminals of solenoid 67 are indicated at 289 and 205 and are respectively connected directly to terminal 221 and the collector of an NPN transistor 299. The emitter of transistor 299 is connected directly to ground at 297 as shown. As long as transistor 299 is conductive and as long as the battery potential is applied across the transistor's emitter and solenoid terminal 289, solenoid 67 will be energized.

By maintaining solenoid 67 energized, the upper end of plunger 66 will be held in the radial hole 65 in collar 64 to thereby prevent rotation of the shutter flap shaft 59. As a consequence, shutter flaps 61 and 62 will be held in their raised positions as long as solenoid 67 is energized.

As shown in FIG. 8, one terminal of a resistor 298 is connected to the base of transistor 299, and one terminal of a resistor 306 is connected to ground at 297. The commonly connected terminals of resistors 298 and 299 are indicated at 296 and are directly connected to terminal 227.

Series connected diodes 304 and 305 are connected in parallel with resistor 306. The anode of diode 304 is connected to the common resistor terminals 296 and thus directly to terminal 227. The cathode of diode 304 is connected to the anode of diode 305, and the cathode of diode 305 is connected to ground at 297. Diodes 304 and 305 maintain a predetermined voltage drop across the emitter and base of transistor 299. This voltage may be 1.2 volts, for example.

Still referring to FIG. 8, one terminal of a resistor 288 is connected directly to the circuit board terminal 221 and to the solenoid terminal 289. The other terminal of resistor 288 is connected directly to the circuit board

terminal 228. Switches 210 are connected in parallel across conductors 208 and 209. In addition, a resistor 284 is connected across conductors 208 and 209 in parallel with switches 210. When switches 210 are open the bias at the base of transistor 299 is determined primarily by resistor 284. When one or more of the switches 210 are closed the bias at the base of transistor 299 is established by diodes 304 and 305 and resistor 298.

Switch 292 may be of any suitable conventional construction and in this embodiment is a Midtex model 618-12B400 time delay switch having a time delay of up to 100 seconds and a timing resistor TR which may be on the order of 20K/Sec.

From the foregoing circuit description it will be appreciated that closure of any one or more of the passenger detection switches 210 shunt resistor 284. Resistors 288, 284 and 298 are connected in series between terminal 221 and the base of transistor 299. Resistors 288, 284 and 306 are connected in series between terminal 221 and ground. Resistors 288, 284 and diodes 304 and 305 are connected in series between terminal 221 and ground. Thus, resistor 284 is in series with resistor 288, resistor 298, resistor 306 and diodes 304 and 305. Likewise, each of the passenger detection switches 210 is in series with resistor 288, resistor 298, resistor 306, and diodes 304 and 305.

As shown in FIG. 8, the movable contactors of switches A₂ and A₃, in addition to being directly connected to the anode of diode 263, are also directly connected to the anode of a further diode 293. The cathode of diode 293 is connected to a time delay switch 292 which in turn is connected through switch 128 to terminal 228. Thus, diode 293 and switches 292 and 128 are connected in series between terminal 228 and the movable contactors of switches A₂ and A₃.

The biasing circuit for maintaining transistor 299 conductive when switches 210 are open may be traced from ground at 297, through emitter and base of transistor 299, through resistor 298, through resistors 284 and 288, through terminal 221, through conductor 213', through connector 192, and through conductor 213 to the positive terminal of the vehicle's battery. It therefore will be appreciated that regardless of the condition of the vehicle's ignition switch or, for that matter, of any switch in the circuit shown in FIG. 8, transistor 299 will be maintained conductive as long as the vehicle battery potential is dropped across ground and terminal 221. Thus, even when the vehicle's ignition switch is turned off, transistor 299 will be maintained conductive. As long as transistor 299 remains in its conductive state, solenoid 67 will be energized to hold shutter flaps 61 and 62 in their illustrated raised positions.

Drain of current from the vehicle's battery is held down by the resistance of solenoid 67. One example of appropriate resistance values for resistors 284, 288, 298 and 306 is indicated in FIG. 8. In this example, resistor 284 is 3.9 K, resistor 288 is 510 ohms, resistor 298 is 51 ohms, and resistor 306 is 5.1 K.

By virtue of the previously described passenger detecting circuit, it will be appreciated that when switch 128 is closed and when one or more of the passenger detecting switches 210 is closed a current path will be established to energize a timing circuit in switch 292. This timing circuit includes resistor TR. After a pre-selected time delay, the timing circuit in switch 292

times out, and switch 292 operates to complete a circuit that energizes motor 89. This motor energizing circuit is established through switch A₂, diode 293, switch 292, switch 128, terminal 228, conductors 208' and 208, the closed passenger detecting switches 210, conductors 209 and 209', terminals 227 and diodes 304 and 305 to ground.

The value of resistor 284 is sufficiently large to prevent sufficient current from being drawn to energize motor 89 when all of the passenger detecting switches 210 are open.

From the foregoing it will be appreciated that when one or more passengers occupy the taxicab, one or more of the passenger detecting switches 210 will close to shunt resistor 284. If the driver does not momentarily depress push button switch 101 to energize motor 90 within the time delay provided by switch 292, switch 292 will become operative upon the pre-selected time delay to complete a circuit for energizing motor 89 for rotation in the forward direction.

This motor energizing circuit may be traced from the positive terminal of the vehicle's battery, through conductors 213 and 214', through terminal 221, through the movable contactor of switch A₁, through contacts 320 and 327 through the windings of motor 90, through contacts 326 and 321, through the movable contactor of switch A₂, through diode 293, through switch 292, through switch 238, through terminal 228, through conductors 208' and 208, through those passenger detecting switches 210 that are closed, through conductors 209 and 209', through terminal 227, and through diodes 304 and 305 to ground. Switch 128 will be closed when cam shaft 97 is in its "for hire" position because of the engagement of switch actuator 126 with cam protrusion 124 and the engagement of actuator 130 with actuator 126.

Thus, motor 89 will be energized for rotation in a forward direction when switch 292 times out, and switch 292 will time out a pre-selected time after any one or more of the passenger detecting switches 210 are closed. Switches 210 are located at appropriate positions in the taxicab to close when one or more passengers enter the cab.

The energization of motor 89 through the circuit that is completed by closure of one or more of the switches 210 will cause cam shaft 97 to rotate from its "for hire" position to its 3 o'clock "hired - waiting time on" position. The initial rotation of cam shaft 97 towards its above-mentioned 3 o'clock position closes switch 118 to complete the holding circuit for maintaining motor 90 energized after switch 128 opens. Switch 128 will open when cam shaft 97 has rotated sufficiently far to move protrusion 124 out of engagement with switch actuator 126. When switch actuator 126 engages either cam surface 122 or cam surface 123, switch 128 will be open. Therefore, switch 128 will be open for all positions of cam shaft 97 except its home or "for hire" position.

Motor 89 will continue to be energized through the holding circuit established by the closure of switch 118 until cam shaft 97 reaches its above-mentioned 3 o'clock position. At this position of cam shaft 97, switch 118 will open to deenergize motor 89 and thereby stop cam shaft 97 at its 3 o'clock position all in the manner previously described. Thus, registration of a fare cannot be avoided by neglecting to momentarily close push

button switch 101 to effect the advancement of cam shaft 97 to its 3 o'clock position.

From the foregoing it will be appreciated that the meter will be placed in its 3 o'clock "hired - waiting time on" mode even the driver does not selectively close push button switch 101 after a passenger enters the taxicab. The fare will therefore be registered and the meter will therefore operate in the manner previously described until the driver actuates push button switch 101 to effect the return of cam shaft 97 to its "for hire" position to clear the fare registers and to reset the meter for its next operation. When cam shaft 97 is returned to its home or "for hire" position the protuberant cam formation 124 again engages actuator 126 to close switch 128.

Any interruption in the circuit for maintaining solenoid 67 energized and hence any interruption in the circuit for maintaining transistor 299 in its conductive state will result in the deenergization of solenoid 67. As a result, the solenoid plunger 66 will be released and will drop down to its deenergized position.

When plunger 66 is downwardly displaced to its solenoid-deenergized position, the upper end of plunger 66 will be removed from hole 65 and hence will disengage from collar 64. A spring 350 peripherally surrounding the lower portion of plunger 66 biases the plunger downwardly to assure that it disengages from collar 64 upon deenergization of the solenoid.

Upon disengagement of plunger 66 from collar 65, the weight of shutter flaps 61 and 62 will rotate shaft 59 counterclockwise as viewed from FIG. 7 so that shutter flaps 61 and 62 will swing to their lowered positions where they cover the total mileage indicator 51, the paid mileage indicator 53, the units indicator 54, the trips indicator 56, and the extras indicator 58. The driver will therefore be unable to record the information provided by these indicators to make the customary accounting at the end of his day. As a result, the absence of this information in the driver's accounting sheet will serve as an indication that the meter may have been tampered with.

Because shutter flaps 61 and 62 are within the enclosure defined by cover 25 and support base 22 they are inaccessible except by removing cover 25. Thus, the only way that shutter flaps 61 and 62 can be raised to record the information on indicators 51, 53, 54, 56 and 58 is to manually lift them up. This, however, requires the removal of cover 25. Removal of cover 25 is un concealably detectable because it is necessary to break the sealed security wire 198 in order to remove the mounting screws 195 that secure cover 25 to base 22.

If solenoid 67 is deenergized by virtue of tampering with the meter, its re-energization will not raise shutter flaps 61 and 62 to their illustrated positions because the deenergization of solenoid 67 results in the complete disengagement of plunger 66 from collar 64.

Solenoid 67 will be deenergized by disrupting the current flow through any one or more of a number of conductors. In particular, solenoid 67 will be deenergized by disconnecting plug 220 from socket 212 or by breaking or grounding any one or more of the conductors 213, 213', 208, 208', 209, 209'.

From the foregoing, it will be appreciated that if a driver attempts to disrupt the passenger detecting circuit, which comprises switches 210, resistor 284, and conductors 208, 209, 208' and 209', transistor 299 will be rendered non-conductive. As a result, the ground

side of the energizing circuit for solenoid 67 will be opened or interrupted to thereby deenergize solenoid 67.

According to a further feature of this invention a reusable mechanical latch 360 (See FIG. 7) is provided for retaining plunger 66 in its raised, energized position to hold shutter flaps 61 and 62 in their raised positions. Latch 360 permits cover 26 to be mounted on and secured to base 22 in the manner previously described before connecting the meter control circuit to the vehicle's battery or some other power source.

As shown in FIG. 7, latch 360 comprises a plunger retaining lever 362, a lever trip pawl 364 and a trip pin 366. Lever 362 is pivotally mounted on a pin 368 for swinging or rocking movement about an axis extending parallel to the rotational axis of cam shaft 97. Pin 368 is fixed to side plate 36. The forward end portion of lever 362 is abuttable with the lower end of plunger 66. As shown in FIG. 7, the rotational axis of shaft 59 is parallel to that of cam shaft 97, and the longitudinal axis of plunger 66 is vertical and normally intersects the rotational axis of shaft 59.

A coiled spring 370 biases lever 362 in a counterclockwise direction (as viewed from FIG. 7) about the axis of pin 368. One end of spring 370 is secured to lever 362, and the other end of spring 370 is anchored to side plate 36.

In FIG. 7, solenoid 67 is energized to hold shutter flaps 61 and 62 in their raised positions, latch 360 is released, and cam shaft 97 is in its "for hire" position. FIG. 7A shows the latching condition of latch 360 for holdplunger 66 in its raised position where it, in turn, holds shutter flaps 61 and 62 in their raised positions.

Trip pawl 364 is in the form of a bell crank having a pair of angularly spaced apart arms 372 and 374. Trip pawl 364 is pivotally mounted on a pin 376 for free swinging or rocking movement about an axis extending parallel to the rotational axis of cam shaft 97.

Pin 366 is mounted on a cam 378. Cam 378 is fixed on cam shaft 97. The purpose of cam 378 is explained in the previously identified U.S. Pat. No. 2,596,164. It will be appreciated that pin 366 may be mounted on any other part that is fixed to and rotatable with cam shaft 97.

When solenoid 67 is deenergized, it is necessary to remove cover 25 from base 22 to manually reset shutter flaps 61 and 62 to their raised positions as previously explained. Solenoid 67 may be deenergized as a result of tampering with the previously described control circuit for the meter, as a result of a defect in the control circuit, or as a result of disconnecting the meter control circuit from the vehicle's battery in order to remove the meter from the taxicab for the purpose of making repairs or inspection. The vehicle battery voltage provides sufficient current for maintaining solenoid 67 energized, but not enough current to pull the solenoid plunger up from its deenergized position to its energized position.

To reset shutter flaps 61 and 62 to their raised positions before cover 25 is remounted on base 22 and to hold the shutter flaps in their raised positions until power is again applied to the control circuit for energizing solenoid 67, the shutter flaps 61 and 62 are first manually raised to the positions shown in FIG. 4, plunger 66 is manually raised to seat the upper end of the plunger in hole 65, and cam shaft 97 is rotated to

its "for hire" position. Lever 362 is then pivoted clockwise to the position shown in FIG. 7A and at the same time, trip pawl 364 is pivoted to seat the lower end of arm 372 in a shallow notch 380 that is formed in the upwardly facing side of lever 362. In the position shown in FIG. 7A, the forward end of lever 362 seats against the lower end of plunger 66 to hold plunger 66 in its raised position where the upper end of the plunger is received in hole 65 of collar 64. Notch 380 is formed in lever 362 near the opposite or rearward end of the lever as shown.

When bellcrank arm 372 is seated in notch 380 as shown in FIG. 7A trip pawl 364 and lever 362 will releasably latch or hold each other against rotation under the combined bias of springs 350 and 370. Thus, plunger 66 is consequently releasably mechanically latched in its raised position by lever 362 where it holds shutter flaps 61 and 62 in their raised positions.

After resetting latch 360 to mechanically, releasably latch shutter flaps 61 and 62 in their raised positions, cover 25 may be mounted on base 22 and secured thereto by screws 195, and a new security wire may be threaded through screws 195 and sealed. Power is then reapplied to the control circuit of FIG. 8 by reconnecting plug 220 to socket 212.

Reconnection of plug 220 with socket 212 again drops the vehicle battery potential across terminal 221 and ground to reenergize solenoid 67. At this stage, solenoid 67 is energized to hold shutter flaps 61 and 62 in their raised position, but latch 360 is still unreleased. Thus, lever 362 and trip pawl 374 are still in the positions shown in FIG. 7A.

The first time that motor 89 is energized to rotate cam shaft 97 from its "for hire" position to its 3 o'clock "hired-waiting time on" position, pin 366 will be advanced counterclockwise as viewed from FIGS. 7 and 7A to strike the upper edge of arm 374 which is in the circular path of rotation of pin 366. As a result, the continued rotation of cam shaft 97 towards its above-mentioned 3 o'clock position will cause trip pawl 364 to swing in a clockwise direction as viewed from FIG. 7A to thereby kick arm 372 out of notch 380. As a consequence, pawl 364 will disengage or unlatch from lever 380, thereby allowing spring 370 to bias lever 362 counterclockwise (as viewed from FIG. 7A) to its position shown in FIG. 7 where the forward, plunger-engaging end of lever 362 is lowered and spaced from the lower end of solenoid plunger 66. Plunger 66 will remain in its raised, shutter-latching position because solenoid 67 was previously energized by reconnecting the control circuit to the vehicle's battery or other electrical power source.

Counterclockwise displacement of lever 362 will be limited by abutment of the notched end of the lever with a pin 382. Pin 382 is fixed to plate 36.

In its position shown in FIG. 7, the forward, plunger-engaging end of lever 362 is spaced below the lower end of plunger 66 by a sufficient distance to allow the upper end of plunger 66 to clear hole 65 and thereby disengage from collar 64 upon subsequent deenergization of solenoid 67. When solenoid 67 is subsequently deenergized, plunger 66 will drop downwardly by gravity and also under the influence of spring 350 to a position where the lower end of plunger 66 seats against the forward end portion of lever 362. In this downwardly displaced or deenergized position of plunger 66, the upper end of plunger 66 will be disengaged from collar

65 to thereby release shutter flaps 61 and 62 for movement to their lowered positions. Engagement of the lower end of plunger 66 with lever 362 prevents plunger 66 from dropping out of the solenoid coil.

Advantageously, the meter is shipped from the factory with the meter in either the 3 o'clock hired mode or the 6 o'clock hired mode and with plunger 66 releasably latched in raised position by latch 360 to hold shutter flaps 61 and 62 in their raised positions. This permits the meter to be connected to a battery to check clockwise and counterclockwise rotation of cam shaft 97. In this condition, cam shaft 97 may be advanced between its 3 o'clock and 6 o'clock positions without tripping lever 362 to its plunger-releasing position. After this check is made power may be removed without causing shutter flaps 61 and 62 to displace to their register-concealing positions.

If the taxicab is not equipped with switches 210 or if it is elected to eliminate the feature of passenger detection (as by disconnecting switches 210 from control circuit 11), a jumper 206 (See FIG. 8A) may be connected across the collector and emitter of transistor 299 within the enclosure that is defined by cover 25 and base 22. As a result, solenoid terminal 205 will be connected directly to ground, and transistor 299 will be removed from the energizing circuit for solenoid 67. With jumper 206, the removal of power from the meter will cause deenergization of solenoid 67.

It will be appreciated from the foregoing description that cover 25 and base 22 form a housing that encloses the metering apparatus together with the various registers 51, 53, 54, 56, 58 and 250a, the control circuit shown in FIG. 8, the solenoid latch assembly comprising solenoid 175, and the mechanical latch assembly 360 for solenoid 175. It also will be appreciated that the housing defined by cover 25 and base 22 is rendered tamperproof by security wire 198. Still further, it will be appreciated that base 22 is electrically conductive metal and is grounded to complete the circuit for all of the grounds for the control circuit in the tamperproof enclosure. In addition, it will be appreciated that any one or more of the previously described registers may be covered or concealed by shutter flaps 61 and 62. Finally, it will be appreciated that collar 65 provides a releasable latch to disengage solenoid 67 from shutter flaps 61 and 62 upon deenergization of solenoid 67.

From the foregoing it will be appreciated that the present invention provides for the following:

1. A novel detection circuit that indicates if exterior circuit connections have been tampered with by concealing one or more of the registers so that the driver cannot record the necessary accounting information which is needed in settling up at the end of a day's run.
2. A novel circuit that particularly detects and indicates such tampering with the passenger detecting circuit that would enable a driver to pocket fares without the appropriate registration of the fares.
3. A novel mechanical latching arrangement for the shutter flaps that obviates the necessity of applying power to the meter control circuit before reassembly of the meter cover on the base of the meter.
4. A novel control arrangement for selectively dispensing only a timed preset amount of "free waiting time" for each hired setting.

5. A novel apparatus whereby the clock or time drive of the meter is utilized to time the amount of "free waiting time" that is selectively dispensed.

6. A novel push button motor control circuit for selectively controlling the direction of rotation of the cam shaft-driving motor.

7. A novel motor control circuit that prevents the driver from skipping any one of the meter's "for hire" and "hired" modes of operation.

8. A novel cam shaft-driving motor control circuit which provides for the selective reversal of the meter's cam shaft, but which prevents reversal of the cam shaft except when the meter is in its "hired-waiting time on" mode.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. In a taximeter, first means having a plurality of registers and an electrical switch-operated control circuit for selectively preventing and providing for the registration of a fare, a housing enclosing said first means, second means including electrical conductor means extending exteriorly of said housing for connecting said control circuit to an electrical current source, and third means enclosed by said housing and rendered effective upon disruption of the connection provided by said conductor means to conceal at least one of said registers, said third means, upon effecting the concealment of said one of said registers, being manually restorable to a register-exposing condition only by entry into said housing.

2. The taximeter defined in claim 1 comprising means for rendering said housing tamperproof.

3. The taximeter defined in claim 1 comprising means disposed exteriorly of said housing for detecting the presence of a passenger in a vehicle equipped with said taximeter, means connecting said passenger detecting means to said control circuit and including electrical conductors extending exteriorly of said housing, said passenger detecting means being effective to condition said first means to provide for the registration of a fare following the detection of the presence of a passenger, and said second means being rendered effective upon disruption of one or more of the circuit connections provided by at least one of said conductors to conceal said one of said registers.

4. The taximeter defined in claim 3 comprising means for rendering said housing tamperproof.

5. The taximeter defined in claim 1 wherein said one of said registers is a mileage-indicating register and wherein another of said plurality of registers provides for the registration of the fare.

6. The taximeter defined in claim 1 wherein said third means comprising a shutter movable between a first position where it exposes said one of said registers and a second position where it conceals said one of said registers, and electrically operated means effective when energized to maintain said shutter in said first position, said electrically operated means being energized by

current flow through said conductor means and being effective upon deenergization to enable said shutter to move from said first position to said second position.

7. The taximeter defined in claim 6 comprising a latch assembly enclosed by said housing and being selectively conditionable to cooperate with said electrically operated means for releasably holding said shutter in said first position when said electrically operated means is deenergized, and means effective upon conditioning said first means to register a fare to release said latch assembly, said shutter being maintained in said first position upon release of said latch assembly only by energization of said electrically operated means.

8. In a taximeter, first means having a plurality of reg-

isters and an electrical control circuit for selectively preventing and providing for the registration of a fare, a housing enclosing said first means, second means dis-

posed exteriorly of said housing for detecting the presence of a passenger in a vehicle equipped with said first means, third means connecting said passenger detect-

ing means to said control circuit and including at least one electrical conductor extending exteriorly of said housing, said second means being effective following the detection of a passenger to condition said first

means for registering a fare, and fourth means enclosed by said housing and effective upon disruption of the connection provided by said at least one conductor to conceal at least one of said registers, said fourth means, upon effecting the concealment of said one of said reg-

isters, being manually restorable to a register-exposing

condition only by detectable entry into said housing.

9. In a taximeter, means having at least first and sec-

ond registers and selectively actuatable switch means for selectively preventing and providing for registration of a fare on said first register, a shutter for at least one of said registers, said shutter being movable between a first position where it exposes said one of said register and a second position where it conceals said one of said registers, a solenoid latch assembly having a solenoid

40 for maintaining said shutter in said first position when said solenoid is energized and being effective upon de-

energization of said solenoid to enable said shutter to move from said first position to said second position, and means for maintaining said solenoid energized independently of actuation of said switch means, said assem-

45 bly having means for unlatching said solenoid from said shutter upon deenergization of said solenoid to prevent said shutter from being moved from said sec-

ond position to said first position upon reenergization of said solenoid.

10. In a taximeter, an apparatus having a plurality of registers and effective to prevent the registration of a fare when in a for hire condition and to provide for the registration of a fare when in a hired condition, an elec-

trical control circuit associated with said apparatus and having selectively actuatable switch means for selec-

tively placing said apparatus in said for hire and hired conditions, a shutter for at least one of said registers, said shutter being movable between a first position where it exposes said one of said register and a second

60 position where it conceals said one of said registers, holding means including an electrically operated device for maintaining said shutter in said first position when said electrically operated device is energized,

65 said holding means being effective upon deenergization of said electrically operated device to enable said shutter to move from said first position to said second posi-

tion, and means adapted to connect said electrically operated device to an electrical current source for maintaining said electrically operated device energized regardless of the condition in which said apparatus is placed by actuation of said switch means and independently of the actuation of said switch means.

11. The taximeter defined in claim 10 wherein said holding means further includes a manually resettable means which upon deenergization of said electrically operated device requires manual resetting before said holding means can be restored to a condition for maintaining said shutter in said first position, said taximeter further comprising a housing enclosing said apparatus, said control circuit, said shutter and said holding means, and said manually resettable means being accessible for resetting only by detectable entry into said housing.

12. The taximeter defined in claim 10 wherein said means for maintaining said electrically operated device energized comprises a first circuit, said taximeter further comprising a second circuit for detecting the presence of a passenger in a vehicle that is equipped with said apparatus and for rendering said control circuit effective following the detection of a passenger to place said apparatus in its hired condition, said first and second circuits having a common portion which when interrupted is effective to deenergize said electrically operated device.

13. In a taximeter, an apparatus having first registers providing information other than fare and a fare recording register, said apparatus being effective to prevent the registration of a fare when in a for hire condition and to provide for the registration of a fare on said fare register when in a hired condition, an electrical control circuit associated with said apparatus and having selectively actuatable switch means for selectively placing said apparatus in said for hire and hired conditions, a shutter for at least one of said first registers, said shutter being movable between a first position where it exposes said one of said first register and a second position where it conceals said one of said first registers, a solenoid, means releasably connecting said solenoid to said shutter to render said solenoid effective to maintain said shutter in said first position when said solenoid is energized, said connecting means being effective to release said shutter from said solenoid upon deenergization of said solenoid, and said shutter being effective upon being released to move from said first position to said second position, the release of said shutter from said solenoid upon deenergization of said solenoid rendering said solenoid ineffective to restore said shutter to said first position, a tamperproof housing enclosing said apparatus, said shutter, said solenoid, said control circuit and said connecting means, and ungrounded conductor means extending exteriorly of said housing to provide for the electrical connection of said control circuit and said solenoid to an exterior electrical current source, said conductor means providing for the supply of energizing current to both said solenoid and said control circuit, the interruption or grounding of said conductor means being effective to deenergize said solenoid.

14. A taximeter for use with a vehicle and comprising a fare recording register, a time drive effective to drive said register at a pre-selected rate during periods when the vehicle is stopped, and means for selectively preventing said time drive from driving said register for

only a preset time period that is timed by said time drive.

15. A taximeter for use with a vehicle and comprising a register for recording fares, first means for advancing said register in accordance with mileage travelled by said vehicle, second means effective when said vehicle is stopped to advance said register at a pre-selected rate, and third means for rendering said second means ineffective to advance said register for only a timed, pre-selected period of time for each fare.

16. In a taximeter having selectable operative and inoperative meter registering conditions, fare indicating means, time responsive means, mileage responsive means, said time responsive means and said mileage responsive means being effective to operate said fare indicating means during the operative meter registering condition to provide for the registration of a fare, and means for selectively preventing only said time responsive means from operating said fare indicating means during registration of a fare for only a preselected period of time.

17. In a taximeter, a register for recording fares, first means including time and mileage drives for said register, second means for selectively placing said first means in a fare-registering condition in which said time and mileage drives are effective to operate said register, and third means cooperating with said second means for selectively preventing said time drive, but not said mileage drive, from operating said register during the registration of a fare for only a pre-selected period of time that is timed by said time drive, said third means being rendered ineffective upon expiration of said time period during registration of a given fare to prevent said time drive from operating said register.

18. In a taximeter, a register for recording fares, first means including mileage and time drives for said register, control means for said first means, said control means being selectively actuatable to render said time and mileage drives effective to operate said register, said time drive including a motor and a gear train, said gear train being shiftable between first and second positions by selective actuation of said control means, said gear train being effective upon being shifted to said first position to operatively connect said motor to said register, and said gear train being effective upon being shifted to said second position to operatively disconnect said motor from said register, a solenoid under the control of said control means and being energized by selectively actuating of said control means to shift said gear train to a third position during the registration of a fare, said motor being operatively disconnected from said register when said gear train is in said third position, and means operatively connected to said motor by said gear train when said gear train is in said third position for effecting deenergization of said solenoid upon the expiration of a pre-selected period of time and for preventing reenergization of said solenoid upon subsequent actuation of said control means for a given fare, and said gear train being effective upon the deenergization of said solenoid to return to said first position for again rendering said time drive effective to operate said register.

19. In a taximeter, a fare recording register, drive means effective to operate said register upon being operatively connected to said register, a cam shaft assembly, a motor for rotating said cam shaft assembly, control means for selectively energizing said motor to pro-

vide for rotation of said cam shaft assembly from a first position to a second position, first cam means forming a part of said assembly for operatively disconnecting said drive means from said register when said assembly is in said first position and for operatively connecting said drive means to said register when said assembly is in said second position, said control means including a selectively actuatable switch for completing a first energizing circuit for said motor, second cam means forming a part of said assembly, switch means forming a part of said control means and cooperating with said

second cam means (a) to complete a holding circuit for maintaining said motor energized upon initial rotation of said assembly from said first position toward said second position, (b) to interrupt said first energizing circuit upon completing said holding circuit, and (c) to interrupt said holding circuit when said assembly reaches said second position to thereby deenergize said motor for stopping said assembly at said second position and preventing reenergization of said motor except by reactuation of said switch.

UNITED STATES PATENT OFFICE
CERTIFICATE OF CORRECTION

Patent No. 3,809,312 Dated May 7, 1974

Inventor(s) Edward C. Warrick, Leo M. Walch, Jr., Dennis R. Hamme

It is certified that error appears in the above-identified patent and that said Letters Patent are hereby corrected as shown below:
